UNITED STATES PATENT OFFICE.

EDMUND C. MORGAN, OF NEW YORK, N. Y.

MINING AND LOADING MACHINE.

1,427,118.

Specification of Letters Patent. Patented Aug. 29, 1922.

Application filed September 30, 1914, Serial No. 864,211. Renewed October 4, 1920. Serial No. 414,556.

To all whom it may concern:

Be it known that I, EDMUND C. MORGAN, a citizen of the United States, residing at New York, in the county of New York and State of New York, have invented certain new and useful Improvements in a Mining and Loading Machine, of which the following is a specification.

My invention relates to improvements in mining machines and has more particular reference to an improved machine for completely severing and removing blocks of coal from the wall of a mine. One of the objects of my invention is to provide a machine of this character which will be simple, durable and reliable in construction and effective and efficient in operation. Other objects of my invention will appear hereinafter.

My invention consists in the construction, combination and arrangement of parts exemplified in the accompanying drawings, set forth in the following description, and embodied in the appended claims.

Referring to the accompanying drawings, Fig. 1 is a view in side elevation of a mining machine embodying my invention, the machine being shown in the position of just beginning the cutting of a block of material from the wall of a mine.

Fig. 2 is a top plan view of the machine shown in Fig. 1.

Fig. 3 is a longitudinal vertical section on the line 3—3 of Fig. 2.

Fig. 4 is a horizontal plane section substantially on the line 4—4 of Fig. 1.

Fig. 5 is a view in front or forward end elevation showing the arrangement of the cutting chain and parts.

Fig. 6 is an enlarged transverse vertical section substantially on the line 6—6 of Fig. 1.

Fig. 7 is an enlarged detail section on the line 7—7 of Fig. 2.

Fig. 8 is an enlarged detail section on the line 8—8 of Fig. 6.

Fig. 9 is a detail section on the line 9—9 of Fig. 6.

Fig. 10 is a detail section through the cutting chain on the line 10—10 of Fig. 6.

Fig. 11 is a detail section on the line 11—11 of Fig. 6.

Fig. 12 is an enlarged view in plan of several links of the cutting chain which embodies my invention and which is used in connection with the machine shown in the other drawings.

Fig. 13 is a view in side elevation looking at the cutting bit side of the chain shown in Fig. 12.

Fig. 14 is a transverse detail section on the line 14—14 of Fig. 12.

Fig. 15 is a detail longitudinal section on the lines 15—15 of Figs. 12 and 14.

Fig. 16 is a view similar to Fig. 1 of the rear portion of the machine showing a modification wherein a conveyor is used for carrying the severed blocks of coal up the inclined runway and discharging them from the machine;

Fig. 17 is a rear end view of the structure shown in Fig. 18.

It will be obvious to one skilled in the art, after having obtained an understanding of my invention from the disclosures herein made, that my invention is capable of modification without departing from the scope and spirit of the invention, and I desire it to be so understood.

The machine which I have shown in the drawings and which embodies my invention, is designed to completely sever crescent-shaped blocks of material from the wall of a mine, break the severed sections or leave them intact as desired, and convey or remove the severed sections to the rear of the machine from which they are discharged. This machine involves certain principles constituting the subject-matter of my co-pending application Serial No. 848,727 filed July 3, 1914, although the present machine also contains other features not embodied in said earlier case.

The operating parts of the machine shown in the drawings are supported by or mounted upon a main frame A which in general is of open-work construction and rectangular in form. This frame is made up wherever possible of structural steel in order to secure comparative lightness in weight, ease of construction, and strength. It has two lower side reaches or members 1 and a cross member 2 at its forward and at its rear end. This rectangular structure forms, in a sense, a base for the frame which may be supported by blocks 3 when the machine is in operating position. Rising from each corner of this horizontal, rectangular base is an upright 4 and these four uprights support at their upper end a rectangular open-work structure similar to the base structure and comprising the upper side reaches or members 5 and the transverse members 6.

This frame arrangement forms a very solid and substantial structure which may be further braced or strengthened if desired by the corner braces 7 and by the triangular plates 8 riveted to the upper and lower ends of the forward uprights and to the upper and lower horizontal reaches 1 and 5. The lower horizontal reaches may, if desired, be provided with horns 9 at their ends to enable the machine to be more conveniently shifted from position to position. A pair of adjustable jacks B are hinged to lugs on the forward upper cross member 6. Between the two sides of the frame is an inclined runway or chute C along which the sections of coal or other material are moved to discharge them from the machine. This chute or runway extends from the lower forward portion of the frame on an incline to the upper rear portion of the machine. It is preferably formed of a large flat plate 10 having upstanding side flanges or rails 11 this being in the form of a large flat plate so as to prevent coal dust or other material from dropping into the driving and other operating parts below. This plate, as shown more clearly in Figs. 2, 3, and 4 is strengthened and supported by a plurality of longitudinal angle beams 12 which rest upon and are secured to the upper rear cross member 6 and the lower forward cross member 2 of the frame. Immediately beneath the forward upper cross member 6 of the frame is a transverse shaft 13 which extends, as shown in dotted lines in Fig. 2, almost the width of the frame. This shaft is supported at one end in a bearing 14 formed in the upper forward corner of the frame and at its other end in a bracket 14^a secured to the crossbeam 6. This shaft supports and constitutes a pivot for a supplemental swinging frame D which, as shown more clearly in Figs. 2 and 3, comprises a long sleeve 15 journaled on the shaft 13 and the outstanding arms 17 and 18. The outer arm 18 and the intermediate arm 17 are joined by a cross member 19 near the inner ends of said arm for the purpose of strength. At the outer ends of the two arms 17 is a long journal sleeve or bearing 20 in which a shaft 21 is mounted. This shaft also has a journal in the outer end of the arm 18. This supplemental frame is swingable in a vertical plane and is adapted to be adjusted in any of its desired positions by means of a device which is positioned between the supplemental frame and the main frame. In the structure shown, this device consists of a sleeve member 22 which is pivoted at one end on a short shaft 23 journaled in one of the frame uprights 4 and in a bracket 24 fastened to the inside of said upright. This sleeve has a smooth bore in which operates a screw 25, the upper end of the screw being pivotally connected at 26 to the arm 18 substantially midway between the ends of said arm. The sleeve 22 is divided into two parts connected together and rigidly held by the bridge 27. The space between the two parts of this sleeve accommodates a nut 28 which operates on the screw 25 to shift the screw longitudinally of the sleeve. Thus by rotating the nut the supplemental frame may be raised or lowered about its pivot shaft 13 and retained in any desired position. The divided sleeve 22 provides an arrangement whereby the adjusting nut 28 will be held in relative position in either direction of movement of the screw 25. The shaft 21 supports the cutting mechanism so that it may be swung upwardly in a vertical plane. The cutting mechanism is in the form of a large open or looped rectangular frame, as shown more clearly in Figs. 2, 5, and 6. This rectangular frame is formed by a substantially U-shaped portion 30, the ends of which are bridged by and fastened to a cross bar or member 31. The outer corners of the U-shaped member 30 are rounded off to facilitate the travel of the chain which will be later explained. The cross member 31 of the cutting mechanism frame has two outstanding members 32 extending substantially in the same plane as the frame and alongside of the arms 17 of the swinging frame 95 D. The faces of these upstanding members 32, as shown in Figs. 2 and 7, have outstanding longitudinal undercut or dove-tailed ribs 33 which fit correspondingly shaped slots in members 34. The members 34 extend transversely to the shaft 21 and are formed with bearings 35 to fit the shaft 21. These members 34, as shown clearly in Fig. 7, are firmly fastened to the shaft 21 by means of splines or keys 36 so that the rotation of the shaft 21 will rotate the members 34. By this construction, the entire cutting mechanism frame is supported by the shaft 21 through the medium of the members 34, and the purpose of the dove-tailed rib 33 and slot connection of the members 32 with the members 34 is to provide an adjustment for the cutting mechanism relatively to the shaft 21. This adjustment determines the diameter of the crescent or arc shaped cut which the cutting mechanism makes. In other words, by adjusting the cutting mechanism relatively to the shaft 21, the radius of the arc which the cutting mechanism makes during the cutting operation may be varied as 115 desired to suit the particular requirements and conditions of the mine in which the machine is operating. In order to secure the cutting mechanism in any position to which it is adjusted, portions of the ribs 33 of members 32 are cut away to provide room for bolt heads 37. The bolts 38 having these heads 37, extend through the members 32 where they carry clamping nuts 39 on their ends. The heads 37 of the bolts are adapted to 130

engage the overhanging flanges of the slots in the members 34 and when the nuts 39 are tightened, the members 34 are clamped tightly against the members 32, thus securely holding the cutting mechanism in its adjusted position. Of course in adjusting the cutting mechanism to any particular size of cut within the range of the machine, the adjustment is preferably obtained by shifting the members 32 relatively to the members 34 so that the cutting mechanism will preferably maintain a constant floor line for the mine. In other words, to adjust the cutting mechanism, it is preferable to place the cutting mechanism, as shown in Fig. 1, in such position that it will start the cutting of the kerf in the plane of the floor line, and then, by means of the adjusting device 25, swing the supplemental frame to the position which will give the desired radius for the cut made by the cutting mechanism. In the present structure, the rotary movement of the cutting mechanism about the shaft 21 as a center, is applied by drums, ropes and mechanisms for operating these parts which will now be described. Adjacent the arm 18 of the supplemental frame D, the shaft 21 carries a segmental drum or sheave 40. This sheave is keyed to shaft 21 to rotate it and hence the cutting mechanism. A rope, cable, or belt 41 is attached at one end 42 to the sheave and in the lowermost position of the cutting mechanism is given a partial turn around the periphery of the sheave. This rope extends downwardly toward the bottom of the frame where it passes beneath an idler sheave 43 which is supported by an upstanding lug or plate 44 secured to the lower side reach of the frame. The rope then passes rearwardly along the side reach of the frame where it is wound upon a large drum 45. This drum is mounted upon a shaft 46. The shaft 46 also carries a large spur gear 47 which is enclosed for protection in a suitable casing 48. The spur gear 47 is adapted to be driven by a pinion 49 loosely mounted upon a shaft 50. The pinion 49 is adapted to be connected with or disconnected from the shaft 50 by means of a clutch member 51 which may be operated in any suitable manner as for instance by means of the yoke 52. The yoke 52 is carried by a rod 53 having at its outer end a handle 54 by which the rod may be rotated. The pinion 49 is also enclosed within the casing 48. The shaft 50 also carries a worm wheel 54 which is driven by a worm 55 on an inclined shaft 56. The shaft 56 in turn is driven by a worm wheel 57 mounted thereon and a worm 58 which as carried on the shaft 59 of a suitable driving motor 60. These last mentioned parts are enclosed in the casing 61 for protection against damage or the entrance of grit. Thus it is seen that the motor, throughout the medium of the mechanism just described,

pulls upon the yoke, cable 41 and this rotates the cutting mechanism in the proper direction and at the proper speed. It will be noted that the adjusting device for the supplemental frame D is positioned substantially in the same vertical plane as the segmental sheave 40 on the shaft 21. It is thus positioned so that it acts as a brace for the supplemental frame to directly take the strains imposed on said frame by reason of the powerful pulling effort exerted by the cable 41 to rotate the cutting mechanism.

The cutting chain E is in the form of a continuous loop which travels around the edge of the U-shaped member 30 of the cutting mechanism frame. This chain comprises a plurality of cutting links 65 and intermediate or connecting links 66. The cutting links are slotted at their ends to accommodate the end portions of the intermediate links. The links of the chain are connected by bolts 67 each cutting link carrying two bolts which pass through the ends of the intermediate links at the ends of said cutting links. These bolts are made removable and they are adapted to be held in position by cross or locking pins 68, (see Figs. 12 to 15). This permits the links of the chain to be removed or replaced whenever desired. At one side each cutting link has an outstanding or lateral lug 69. These lugs and the links on which they are formed, are provided with long channels or sockets 70 for the reception of the shanks 71 of cutting bits 72. These cutting bits project beyond the lugs and are pointed in the direction in which the chain travels so as to cut into the material. The sockets 70 are placed at an angle with respect to the plane of the chain and the several bits are staggered with relation to each other, in other words, alternate sockets are angled in opposite directions. This arrangement holds the bits at an angle and causes them to cut a kerf somewhat wider than the thickness of the frame and chain so that they will not bind as they enter the kerf. Each bit may be removably fastened in position by means of a set screw 73. The U-shaped frame portion 30 of the cutting mechanism has a peripheral flange or ledge 74 upon which the chain travels and by which it is supported. The chain is locked against displacement with respect to the frame by means of small plates 75 which are riveted to lugs 76 formed on the side of the cutting links opposite to that from which the bits project. These plates engage the flanges 77 of plates 78 fastened in any suitable manner to the portion 30 of the cutting mechanism frame. The plates 78 and the flanges 74 form undercut channels or slots around the edge of the portion 30 of the frame, and the plates 75 travel in these slots and hold the cutting chain in position. It will be understood that sufficient clearance

should be provided for the free travel of the plates 75 throughout their entire range of movement. For this purpose the grooves formed by the flange 77 should be in proper alignment entirely around the stirrup frame, and the sprocket wheel 80, shown in Figs. 8 and 11, should be so located as to minimize friction while pulling the chain out of the groove. The sprocket wheel 80 should also be so located as to provide sufficient clearance for free movement of the chain and the extension plates 75 thereon. At one corner of the cutting mechanism frame (see Fig. 5) the cross member 31 of said frame has an arc-shaped rib 79 to facilitate the operation of the chain at this corner. At the opposite corner the chain travels around a sprocket 80 by which it is driven. Between the sprocket and the arc-shaped member 79 the chain is allowed considerable slack which is intended to permit the tautness of the chain to be adjusted as desired. The sprocket 80 which drives the chain, is mounted on and keyed to the long hub of a beveled gear 82 which is loosely mounted by a suitable bearing on a stationary shaft 81. The beveled gear 82 meshes with and is driven by a corresponding beveled gear 83 loosely mounted by a suitable bearing on a short stationary shaft 84. The gear 83 has an extended hub on which is keyed a spur gear 85. This gear meshes with and is driven by a similar gear 86 on a shaft 87 which is parallel with the shaft 84. The shaft 87 carries at its outer end a beveled gear 88 which is driven by a beveled pinion 89 mounted on the upper end of the long shaft 90. One of the outstanding members 32 on the cutting mechanism frame, is arranged so as to form an enclosure or casing 32^a for the several gears and shafts just described. This casing contains bearings, of course, for the shafts and its purpose is to prevent coal dust or other grit from damaging the various driving gears. The casing 32^a as shown more clearly in Figs. 9 and 11, is divided in the plane of the axes of the two shafts 84 and 87 so as to permit the assembling and disassembling of the parts whenever desired. One portion 32^b of this enclosure or casing, is in the form of a cap which is removably fastened to the portion of the casing 32^a by means of the bolts 32^c (Figs. 7 and 11). One of the bolts 38 which assists in clamping the member 32 with the member 34, is lengthened and extends through the cap 32^b, otherwise it is similar to the remaining bolts 38. By reference to Fig. 6, it will be observed that an extension portion 32^d of a casing 32^a forms a bearing for another casing 92 which encloses the beveled gears 88 and 89 and also a portion of the shaft 90. The shaft 90, through the various other shafts and gears just described, operates to drive the cutting

chain around its frame. It will be noted, however, that although the shaft 87 is offset with respect to the shaft 21, which constitutes the center of rotation of the cutting mechanism, the ability of the casing 92 to rotate on the bearing 32^d permits the shaft 90 to accommodate itself to the rotary movement of the cutting mechanism. In other words, the driving connection between the shaft 90 and the shaft 87 is adaptable to the relative positions assumed by the shaft and cutting mechanism during the operation of the machine, and the shaft 90 will thus always effectively transmit power to the cutting mechanism irrespective of its relative position. The casing 92 may be split longitudinally along the line 93 to permit its assembling and disassembling as desired. The motor shaft 59 extends from the motor 60 and carries a beveled gear 94 which drives another beveled gear 95. The gear 95 is mounted on the shaft 90. It has a long sleeve 96 which is journaled in the bearing 97 and which is splined to the shaft 90 in such a manner that it will drive the shaft but will permit the shaft 90 to slide longitudinally thereof. This maintains a driving connection between the motor shaft and the shaft 90 regardless of the movement of the shaft necessary to accommodate itself to the rotation of the cutting mechanism. The bearing 97 is part of a casing which encloses the gears 94 and 95. This casing is journaled at 98 on a bearing formed on the motor frame and surrounding the motor shaft so that it will permit the operation of the shaft 90.

Attached to the U-shaped member 30 of the cutting mechanism frame, is a plurality of ropes or cables 100 which are substantially equally-spaced apart and parallel, as shown more clearly in Figs. 2, 3, and 4. These ropes may be fastened in any suitable way to the cutting mechanism frame, as by means of the connections 101. These ropes or cables extend from the cutting mechanism frame up the inclined chute or runway C and pass around sheaves 102 at the extreme upper rear end of the runway C. These sheaves are suitably mounted on a transverse shaft 103 which is journaled in depending lugs 104 on the upper end of the runway. From these sheaves the cables 100 extend forwardly where they are wound upon a plurality of individual drums 105 mounted on the transverse shaft 106 disposed beneath the chute or runway C. These drums are all fastened on the shaft or keyed to the shaft to rotate in unison. The shaft is journaled in bearings 106^a outstanding from the motor 60. The shaft also carries a worm wheel 107 which meshes with a worm 108. The worm 108 is loose on the shaft 56 which, as before explained, is driven from the motor. It is adapted to be con-

nected with or disconnected from the shaft 56 by means of a clutch member 109, as shown more clearly in Fig. 3. This clutch member may be actuated by the operator by 5 means of a clutch shifting device. This clutch shifting device, as shown more clearly in Figs. 3 and 4, has an arm 110 which engages the clutch member and which is mounted upon a shaft 111, the shaft being 10 pivoted in suitable bearing lugs depending from the bottom of the chute or runway C. The rock shaft 111 carries at its outer end, an operating member 112 in a convenient position for the operator. The worm wheel 15 107 and the worm 108 are enclosed in a suitable casing 113 which is supported by a cross member 114 on the frame of the machine. One of the ropes or cables 100 passes over 20 an idler sheave 114^a which raises this rope clear of the feeding mechanisms previously described. It will thus be seen that when the cutting mechanism is rotated and cuts a crescent or arc-shaped kerf in the wall of the mine, it necessarily pulls the ropes or 25 cables 100 into the kerf behind itself, so that these ropes, as shown more clearly in Fig. 3, embrace the section of coal cut by the cutting mechanism. The section of coal will drop upon these belts or ropes 100 and it may 30 drop as a whole section or it may break into several parts, depending, of course, upon the nature and condition of the coal, but in any event, the throwing of the clutch 109 will 35 connect the drums into operating relation to the shaft 56 and tension will be applied to the conveyor ropes 100 to pull the section or pieces of coal up the inclined runway and 40 discharge them from the rear end of the machine. Or the section of coal may be intentionally broken during or at the finish of the cutting operation if desired, by applying tension to the ropes at the same time that the cutting mechanism is rotating upwardly. This tension may be applied to the ropes 45 100 by any suitable means, such as a brake, which I have shown more clearly in Figs. 1 and 4. This brake comprises a drum 115 on the shaft 106 and a band 116 embracing said drum. The band may be tightened against 50 the drum by means of an operating foot lever 117 which is mounted upon a lug up-standing from the cross member 114 of the frame. Since the ropes embrace the section, the tension applied to the ropes will act upon 55 the section of coal to break it. The ropes 100 are thus employed not only to break and remove the section of coal, but also to restore the cutting mechanism to its initial position. When tension is applied to the ropes 100 by 60 the throwing in of the clutch 109, the clutch member 51 will of course be thrown so as to disconnect the power drum 45 from the driving power, as previously explained. It is desirable that the cutting mechanism be capable of being returned or restored to its

initial position at a comparatively greater rate of speed than that of its cutting operation, and for this reason I make the worm 108 and the worm wheel 107 of such proportions that the proper speed ratio may be obtained. This worm and gear 108 and 107, are also arranged so that when the cutting mechanism is cutting the kerf and hence pulling upon the ropes 100, the gear 107 will drive the worm 108, but this worm will be disconnected from the shaft 56 by the clutch 109 and will therefore run idly. It is thus seen that as each section of coal is cut and removed from its original position by the conveyor ropes 100, it is carried up the inclined runway by said ropes, the succeeding sections assisting in pushing up the incline those which preceded them. In order to avoid any possibility of the sections slipping back down the incline, while the cutting mechanism starts forward for another cut, the bottom of the chute may be provided with a plurality of clutching devices. These may be in the nature of small dogs 120 projecting through suitable openings in the 90 plate 10 of the runway. These may be pivoted at 121 beneath the plate 10 and yieldingly held in their projected position by a spring 122. They are pointed in such direction that they will yield as the sections pass up the inclined runway, but will resist the downward movement of the blocks or sections.

If desired, an additional conveyor may be provided in the runway C to carry the sections up the incline and discharge them from the rear end thereof. In Figs. 18 and 19 I show a modified construction in which a conveyor is employed. This conveyor may be in the form of a plurality (preferably 2 or more) of continuous chains 130 having flights 131 thereon at intervals. These chains travel around sprockets 132 at the upper end of the runway. In this case, the sprockets may be mounted upon the transverse shaft 110 103 and positioned between the ropes 100. At the lower end of the runway the chains travel around sprockets 133 which are mounted upon a transverse shaft 134. One of the chains may pass over an idler 135 beneath the runway bottom 10 in order to clear the feed mechanism. The end of the shaft 56 may be provided with a beveled gear 136 which meshes with and drives a beveled gear 137 on a transverse shaft 138 journaled 115 in suitable bearings in the rear uprights of the frame. This shaft also carries sprockets 139 around which the conveyor chains 130 travel and by which said chains are driven from the shaft 138. 120

I claim:

1. The combination with a frame, of cutting mechanism mounted thereon, means for operating said cutting mechanism in a vertical direction to cut a solid core of material 130

from a mine wall, and apparatus comprising flexible means connected to said frame and adapted to be moved into the kerf cut by said cutting mechanism and engage the cut material directly for removing the same rearwardly.

2. The combination of cutting mechanism having an unobstructed core opening therethrough for severing a solid core of material from the wall of a mine and movable in a vertical direction, and means adapted to be moved into the kerf cut by said cutting mechanism for removing the core rearwardly and for restoring the cutting mechanism to its initial position.

3. The combination of a vertically rotatable cutting mechanism for cutting a section of material from a mine wall, means attached to and adapted to be drawn into the kerf by the cutting mechanism, and means for pulling upon the aforesaid means for simultaneously removing a severed section of material rearwardly along the reverse line of movement of said cutting mechanism and simultaneously restoring the cutting mechanism to initial position.

4. The combination of a vertically rotatable cutting mechanism arranged to completely sever a section of material from the wall of a mine, a frame supporting said cutting mechanism, a flexible member attached to the cutting mechanism adapted to be drawn into the kerf thereby behind the cutting mechanism in direct engagement with the severed section, a drum for pulling upon the flexible member in the opposite direction to remove the severed section, and means for driving said drum.

5. The combination of a vertically rotatable cutting mechanism arranged to completely sever a section of material from the wall of a mine, a frame supporting said cutting mechanism, a flexible member attached to the cutting mechanism adapted to be drawn into the kerf thereby behind the cutting mechanism to embrace the severed section, a drum for pulling upon the flexible member in the opposite direction to remove the severed section, means for driving said drum, and a runway extending to the rear of the frame and along which the severed section is moved by the flexible member.

6. The combination of a frame, a supplemental frame movable thereon, a cutting mechanism supported by said supplemental frame and rotatable vertically to completely sever a crescent-shaped section of material from the wall of a mine, a flexible belt attached to said cutting mechanism adapted during the cutting operation thereof to be drawn into the kerf and to embrace the severed section, means for pulling upon said belt to convey the severed section rearwardly and to restore the cutting mechanism to initial position, and an inclined runway ex-

tending to the rear of the frame and upon which said flexible belt moves the severed section.

7. The combination of a main frame, a supplemental frame hinged on the forward end of the main frame and rotatably adjustable on its hinge, a loop cutting mechanism rotatably mounted in a vertical plane on the supplemental frame and arranged to completely sever a crescent-shaped block of material from the wall of a mine, a flexible belt, means actuating said belt to rotate the cutting mechanism in the cutting direction, a second belt attached to the cutting mechanism and adapted to be drawn into the kerf and around the severed section, means for pulling said second belt in the opposite direction to restore the cutting mechanism and to convey the severed section longitudinally, and an inclined runway for directing the moving section of material to the rear of the machine.

8. The combination of a main frame, a supplemental frame hinged on the forward end of the main frame and rotatably adjustable on its hinge, a loop cutting mechanism rotatably mounted in a vertical plane on the supplemental frame and arranged to completely sever a crescent-shaped block of material from the wall of a mine, a flexible belt, means actuating said belt to rotate the cutting mechanism in the cutting direction, a second belt attached to the cutting mechanism and adapted to be drawn into the kerf and around the severed section, means for pulling said second belt in the opposite direction at greater speed to restore the cutting mechanism and to convey the severed section longitudinally, and an inclined runway for directing the moving section of material to the rear of the machine.

9. In a mining machine, the combination with a frame, of a supplemental frame rotatably mounted thereon, loop chain cutting mechanism rotatably suspended from said supplemental frame on an axis extending in a general horizontal direction, and means for moving said supplemental frame radially to adjust the path of travel of said cutting mechanism.

10. The combination of a main frame, a supplemental frame mounted thereon, loop chain cutting mechanism rotatably suspended from said supplemental frame on a horizontal axis, and means for varying the position of said supplemental frame to adjust the elevation of said horizontal axis and the distance of the path of travel of the cutting mechanism from the center of rotation.

11. The combination of a main frame, a supplemental frame hinged on the forward portion of said main frame, loop chain cutting mechanism rotatably and adjustably mounted on said supplemental frame on a horizontal axis, and means for relatively

- moving said supplemental frame and loop chain cutting mechanism to vary the radial cutting range of the latter relatively to such horizontal axis.
- 5 12. In a mining machine, the combination with a main frame, of a supplemental frame pivotally mounted on said main frame on a horizontal axis for oscillatory movement relatively to said main frame, loop chain 70 core cutting mechanism having an unobstructed core opening therethrough and pivotally mounted on a horizontal axis at the other end of said supplemental frame for oscillatory movement relatively to said supplemental frame, and means for adjusting the supplemental frame about its pivotal connection to said main frame to adjust the position of said loop chain core cutting mechanism.
- 10 13. A mining machine adapted to cut cores of material in a mine chamber from the floor to the roof thereof, comprising a main frame, a supplemental frame pivoted at one end on a horizontal axis to said main frame, loop chain core cutting mechanism having an unobstructed core opening therethrough and rotatably mounted on a horizontal axis at the other end of said supplemental frame for swinging movement from the floor to 75 the roof of the mine chamber, and a rigid adjustable brace for swinging the supplemental frame about its pivot and holding it in its adjusted position.
- 15 14. In a mining machine, the combination with a main frame, of a supplemental frame pivoted at one end on a horizontal axis to said main frame, loop chain core cutting mechanism mounted to swing on a horizontal axis at the other end of said supplemental frame, means for adjusting the supplemental frame about its pivot relatively to said main frame to adjust the height of said loop chain core cutting mechanism, a drum attached to said cutting mechanism, a belt 80 wound on said drum, and means for applying tension to said belt to swing said cutting mechanism on its pivotal connection to said supplemental frame.
- 20 15. In a mining machine, the combination with a main frame, of a supplemental frame pivoted at one end on a horizontal axis to said main frame, loop chain core cutting mechanism rotatably mounted on a horizontal axis at the other end of said supplemental frame, means for adjusting the supplemental frame about its pivotal connection to said main frame to vary the height of said loop chain core cutting mechanism, a drum attached to said cutting mechanism, a belt 85 wound on said drum, means for applying tension to said belt to rotate said cutting mechanism to effect the feed thereof, a shaft extending to said cutting mechanism, a driving connection between the said shaft and said cutting mechanism, and means 90 for operating said cutting mechanism including pivotal feeding movement on said supporting frame, a driven shaft, a mounting movable bodily with the cutting mechanism for supporting said driven shaft in a position offset with respect to the pivotal axis of said cutting mechanism, and driving connections between said driven shaft and the chain of said cutting mechanism.
- 25 16. In a mining machine, the combination with a main frame, of a prime mover mounted on said main frame, a supplemental frame adjustably mounted on said main frame, core cutting mechanism having an unobstructed core opening therethrough and pivotally mounted on said supplemental frame 95 for arcuate feeding movement, and means for operating said core cutting mechanism in its various adjusted positions, comprising flexible bevel geared driving connections between said main frame and said core cutting mechanism.
- 30 17. In a mining machine, the combination with a main frame, of a source of power mounted thereon, core cutting mechanism having an unobstructed core opening therethrough and mounted to swing on a horizontal axis relatively to said main frame, said core cutting mechanism embodying a continuous travelling cutting chain, means for feeding said core cutting mechanism by 100 swinging the same relatively to said main frame, and flexible driving connections between said source of power and said chain for driving the latter during the feed thereof to sever a large section of material from a mine wall.
- 35 18. In a mining machine, the combination with a main frame, of a source of power mounted thereon, core cutting mechanism having an unobstructed core opening therethrough and mounted to swing on a horizontal axis relatively to said main frame, said core cutting mechanism embodying a continuous travelling cutting chain, means for feeding said core cutting mechanism by 105 swinging the same relatively to said main frame, and flexible driving connections between said source of power and said chain for driving the latter during the feed thereof to sever a large section of material from 110 a mine wall.
- 40 19. In a mining machine, the combination with a supporting frame, of kerf cutting mechanism mounted on said frame to swing on a substantially horizontal axis, and embodying a continuous cutting chain occupying a single plane substantially radial to the center of rotation of said cutting mechanism, said cutting mechanism having an unobstructed core opening therethrough, a source 115 of power on said main frame, means at one side of said cutting mechanism for swinging the latter on such horizontal axis to effect feeding movement of said cutting mechanism, and flexible driving connections between said source of power and the other side of said cutting mechanism for actuating said chain during the swinging feed thereof to effect the cutting of an upright core in a mine wall.
- 45 130

20. In a mining machine, the combination with a supporting frame, of core cutting mechanism having an unobstructed core opening therethrough and mounted on said supporting frame for pivotal movement of a substantially horizontal axis and embodying a continuous chain cutter occupying a single plane substantially radial to the center of rotation of said cutting mechanism, means at one side of said cutting mechanism for rotating it as a whole to effect arcuate feeding movement thereof, a source of power on said supporting frame, a shaft connected to said source of power, and means offset with respect to the center of rotation of the cutting mechanism for getting power from the shaft to the chain during the feeding movement of said cutting mechanism to effect the cutting of an upright core in a mine wall in advance of said frame.

21. The combination of a frame, a rotary cutting mechanism positioned at the forward end of said frame to swing on a horizontal axis and arranged to cut an upright crescent-shaped section of material from a vertical wall of a mine in front of said frame, flexible means adapted to be drawn into the kerf by said cutting mechanism and embrace the section of material, and means for pulling upon said flexible member to restore the cutting mechanism and remove the section of material.

22. The combination of a frame, a rotary cutting mechanism positioned at the forward end of said frame to swing on a horizontal axis and arranged to cut an upright crescent-shaped section of material from the wall of a mine, a cable attached to the cutting mechanism to be drawn into the kerf by the rotation thereof into direct engagement with the cut section of material, and means at the rear of the machine for pulling upon said cable to restore the cutting mechanism and discharge the section from the rear end of the frame.

23. The combination of a frame, a runway extending from the forward to the rear end of the frame, rotary cutting mechanism positioned at the forward end of the runway and arranged to sever a crescent-shaped section of material from a vertical wall of a mine in front of said frame, a plurality of flexible members extending along the runway and attached to the cutting mechanism to be drawn into the kerf thereby, and means for pulling said flexible members to restore the cutting mechanism and discharge the severed section from the rear of the frame.

24. The combination of a frame, a runway extending from the forward to the rear end of the frame, rotary cutting mechanism positioned at the forward end of the runway and arranged to sever a crescent-shaped section of material from the wall of a mine, a plurality of flexible members extending along

the runway and attached to the cutting mechanism to be drawn into the kerf thereby into direct engagement with the cut section of material, a drum beneath said runway and about which the flexible members are wound, 70 and means for actuating said drum to apply tension to the flexible members,

25. The combination of a frame, a runway extending from the forward to the rear end of the frame, cutting mechanism positioned at the forward end of the runway and arranged to sever a crescent-shaped section of material from the wall of a mine, a plurality of flexible members extending along the runway and attached to the cutting 80 mechanism to be drawn into the kerf thereby into direct engagement with the cut section of material, a drum beneath said runway and about which the flexible members are wound, and means in said runway for 85 restraining the movement of the sections toward the forward end of the runway.

26. The combination of a frame, an inclined runway extending from the forward to the rear end thereof, rotary cutting 90 mechanism positioned at the forward end of said runway, means for rotating said cutting mechanism, a plurality of winding drums positioned beneath the runway, a plurality of conveyor ropes extending from said 95 drums along the runway and attached to the cutting mechanism and adapted to be pulled into the kerf by the cutting mechanism into direct engagement with the cut section of material, a source of power, and 100 means for connecting said drums to the source of power to apply tension to the ropes and restore the cutting mechanism.

27. The combination of a frame, an inclined runway extending from the forward 105 to the rear end thereof, rotary cutting mechanism positioned at the forward end of said runway, means for rotating said cutting mechanism, a plurality of winding drums positioned beneath the runway, a plurality of 110 ropes extending from said drums along the runway and attached to the cutting mechanism and adapted to be pulled into the kerf by the cutting mechanism into direct engagement with the cut section of material, a 115 source of power, and means for applying tension to the ropes during the rotation of said cutting mechanism in the cutting direction.

28. The combination of a frame, an inclined runway extending from the forward 120 to the rear end thereof, rotary cutting mechanism positioned at the forward end of said runway, means for rotating said cutting mechanism, a plurality of winding drums positioned beneath the runway, a plurality of 125 ropes extending from said drums along the runway and attached to the cutting mechanism and adapted to be pulled into the kerf by the cutting mechanism into direct engagement with the cut section of material, 130

- a source of power, means for connecting said drums to the source of power to apply tension to the ropes and restore the cutting mechanism, and means for driving said drums, pulling said ropes and restoring the cutting mechanism at a greater speed.
29. The combination of a main frame, an adjustable supplemental frame pivoted on said main frame on a horizontal axis, a substantially rectangular open cutting mechanism frame pivoted on a horizontal axis on said supplemental frame, means for adjusting said cutting mechanism frame relatively to the center of rotation thereof, and a continuous cutting chain travelling around the edge of said cutting mechanism frame to produce an incision in a mine wall leaving a solid core.
30. The combination of a main frame, an adjustable supplemental frame pivoted on said main frame on a horizontal axis, a substantially rectangular open cutting mechanism frame pivoted on a horizontal axis on said supplemental frame, means for adjusting said cutting mechanism frame relatively to the center of rotation thereof, a continuous cutting chain travelling around the edge of said cutting mechanism frame to cut a solid core from a mine wall, means at one side of said cutting mechanism frame for rotating the frame, and means at the other side of said cutting mechanism frame for driving the chain.
31. The combination of a main frame, an adjustable supplemental frame pivoted on said main frame on a horizontal axis, a substantially rectangular open cutting mechanism frame pivoted on a horizontal axis on said supplemental frame, means for adjusting said cutting mechanism frame relatively to the center of rotation thereof, a continuous cutting chain travelling around the edge of said cutting mechanism frame, means at one side of said cutting mechanism frame for rotating the frame, means at the other side of said cutting mechanism frame for driving the chain, a plurality of conveyor ropes attached to said cutting mechanism frame to be drawn into the kerf and extending to the rear end of the main frame, and means for pulling upon said conveyor ropes to restore the cutting mechanism to initial position and convey the severed section of material to the rear of the machine.
32. The combination of a main frame, an adjustable supplemental frame pivoted on said main frame on a horizontal axis, a substantially rectangular open cutting mechanism frame pivoted on a horizontal axis on said supplemental frame, means for adjusting said cutting mechanism frame relatively to the center of rotation thereof, a continuous cutting chain travelling around the edge of said cutting mechanism frame, means at one side of said cutting mechanism frame for rotating the frame, means at the other side of said cutting mechanism frame for driving the chain, a plurality of conveyor ropes attached to said cutting mechanism frame to be drawn into the kerf and extending to the rear end of the main frame, means at the other side of said cutting mechanism frame for driving the chain, a plurality of conveyor ropes attached to said cutting mechanism frame to be drawn into the kerf and extending to the rear end of the main frame, means for pulling upon said conveyor ropes to restore the cutting mechanism to initial position and convey the severed section of material to the rear of the machine.
33. In a mining machine, the combination with a supporting frame, of loop chain core cutting mechanism mounted on the forward end of said frame to swing on a horizontal axis, said core cutting mechanism having an unobstructed core opening therethrough, means for operating said loop chain core cutting mechanism including feeding movement thereof relatively to said frame to cut a core in a mine wall adjacent said frame, and means for adjusting the position of the entire loop chain core cutting mechanism relatively to said supporting frame to vary the height of the core cut in the mine wall by said cutting mechanism adjacent said frame.
34. The combination of a main frame, a supplemental frame mounted thereon, cutting mechanism suspended from said supplemental frame on a substantially horizontal axis to cut a solid core of material from a mine wall in a vertical direction, and means for adjusting said supplemental frame to vary the height of said horizontal axis of rotation of said cutting mechanism.
35. In a mining machine, the combination with a supporting frame, of a source of power mounted thereon, core cutting mechanism mounted on said supporting frame in position for cutting an upright core in a mine wall adjacent said supporting frame, means for bodily adjusting said core cutting mechanism to vary the up and down cutting range thereof relatively to said supporting frame, and flexible driving connections between said source of power and said core cutting mechanism adaptable to the adjustment of said cutting mechanism to effect the transmission of power to said cutting mechanism in its various adjusted positions.
36. In a mining machine, the combination with a supporting frame, of loop chain core cutting mechanism having an unobstructed core opening therethrough and mounted for swinging movement relatively to said frame on an axis extending in a general horizontal direction, means for swinging said loop chain core cutting mechanism to effect feeding movement thereof, and mechanism for adjusting the position of the axis of swing of said loop chain core cutter relatively to said supporting frame to vary the range of

operation of said loop chain core cutter relatively to said supporting frame.

37. In a mining machine, the combination with a supporting frame, of loop chain core cutting mechanism mounted on said frame to swing in an upright arc on a horizontal axis, means for operating said loop chain core cutting mechanism to cut a solid core of material from a mine wall between the floor and the roof of a mine chamber, and mechanism for adjusting the height of such horizontal axis to a position approximately midway between the said floor and roof, to adapt the machine to cutting cores between the floor and roof of any one of various mine chambers in which the heights of the ceilings vary.

38. In a mining machine, the combination with a supporting frame, of a core cutter pivotally mounted on said frame to swing on an axis extending in a general horizontal direction, and means for shifting vertically the said pivot of said core cutter relatively to said supporting frame to vary the cutting range of said core cutter.

39. In a mining machine, the combination with a main frame, of a rotary loop chain core cutter mounted on said main frame to swing on a horizontal axis, means for operating said core cutter to cut a solid core of material from a mine wall adjacent said frame, and means for shifting the elevation of the center of rotation of said core cutter relatively to said frame to vary the cutting range of said cutter relatively to said frame.

40. The combination of a frame, cutting mechanism rotatable on a horizontal axis thereon embodying a frame having an unobstructed core opening therethrough and a chain cutter travelling thereon, and means for adjusting bodily said frame and cutting chain relatively to the axis of rotation of said cutting mechanism.

41. In a mining machine, the combination with a supporting frame, of core cutting mechanism mounted to swing on a horizontal axis on said supporting frame, means for operating said core cutting mechanism including swinging feeding movement thereof to cut a solid core of material from a mine wall adjacent said frame, and means for adjusting the elevation of the center of swing of said core cutting mechanism relatively to said frame to vary the cutting range of said core cutting mechanism relatively to said supporting frame while the latter remains stationary.

42. In a mining machine, the combination with a supporting frame, of cutting mechanism mounted on a horizontal axis for articulate swinging movement relatively to said frame, a rope drum connected to said cutting mechanism to move bodily therewith, a rope connected to said drum and extending around the same, means for exerting a pull

on said rope to effect swinging feeding movement of said cutting mechanism, and an adjustable brace supporting device mounted on said supporting frame in position to support said cutting mechanism with the said horizontal axis in various positions relatively to said supporting frame.

43. In a mining machine, the combination with a main frame, of a supplemental frame mounted on said main frame for movement relatively thereto, a shaft on said supplemental frame, cutting mechanism mounted on said shaft, a large sheave at one end of said shaft, a rope connected to said sheave and extending around the same, means on said main frame for pulling said rope to effect the swinging of said cutting mechanism to feed the same, means for actuating said cutting mechanism during the feeding movement thereof, and an adjustable brace between said main frame and said supplemental frame for holding the latter rigidly in adjusted position during the operation of said cutting mechanism.

44. The combination of a frame, an inclined run-way supported by said frame, loop chain cutting mechanism at the forward end of said run-way, operating mechanism positioned beneath said run-way, a cable extending from said operating mechanism to the cutting mechanism for swinging the cutting mechanism, and a cable extending from said operating mechanism to the cutting mechanism for restoring said cutting mechanism.

45. In a mining machine, the combination with a frame, of an inclined platform, cutting mechanism positioned at the forward end of said platform to cut a core of material from a vertical mine wall, a cable extending from the cutting mechanism, a drum beneath said platform for pulling said cable to rotate the cutting mechanism, a plurality of additional drums positioned beneath said platform, a plurality of belts extending from said additional drums to the rear end of the platform and thence along the latter to the cutting mechanism for restoring the cutting mechanism, and a source of power for driving said first named rope drum and said additional rope drums.

46. In a mining machine, the combination with a supporting frame, of core cutting mechanism mounted thereon and having an unobstructed core opening therethrough, means for operating said core cutting mechanism including swinging feeding movement thereof on a horizontal axis having a predetermined relation to said supporting frame, means for restoring the core cutting mechanism to approximately initial position, and a motor common to said operating means and said restoring means.

47. In a mining machine, the combination with a swinging loop chain cutting mecha-

- nism having an unobstructed core opening therethrough, of means for operating said cutting mechanism including the feed thereof to cut a solid core of material from a mine wall, means for restoring said cutting mechanism, a common driving motor, a locking worm driving connection between the motor shaft and the cutting mechanism operating means, and a non-locking worm driving connection between the motor shaft and the restoring means. 5
48. In a mining machine, the combination with vertically swinging loop chain core cutting mechanism, of means for operating said cutting mechanism including the feed thereof to cut a core of material from a mine wall, means for restoring the cutting mechanism, a common driving motor, a locking worm driving connection between the motor shaft and the cutting mechanism operating means, a non-locking worm driving connection between the motor shaft and the restoring means, and means for connecting and disconnecting said non-locking connection at will. 10
49. A mining machine comprising a U-shaped frame having an unobstructed core opening therethrough, a travelling endless loop chain cutter mounted on said U-shaped frame, a swinging frame, a horizontal shaft for supporting said swinging frame, means for adjustably securing said U-shaped frame radially to said swinging frame, a supporting frame for said shaft, said supporting frame comprising forwardly extending arms to give freedom of movement of said U-shaped frame throughout approximately a semi-circle in advance of said shaft and said supporting frame, means for actuating said chain cutter by causing the same to travel along said U-shaped frame transversely to the feeding path of travel thereof, and apparatus for feeding the chain cutter during the actuation thereof, by swinging said U-shaped frame transversely to the path of travel of said chain cutter thereon. 15
50. In a mining machine, the combination with a frame, of means mounted thereon for cutting an upright core in a mine wall from a position near the floor of the mine chamber toward the roof thereof, said cutting means having an unobstructed core opening therethrough, mechanism for operating said cutting means, and mechanical apparatus acting on the cut material when dislodged for taking it back from the mine wall along said frame. 20
51. In a mining machine, the combination with loop chain core cutting mechanism having an unobstructed core opening therethrough and mounted for up and down swing on a substantially horizontal axis, of means for operating said loop chain core cutting mechanism including upward feed thereof toward the roof of the mine chamber 25
- to cut an upright core in an upright mine wall, and loading apparatus in position for moving the severed material from the mine wall immediately after being dislodged therefrom by said core cutting mechanism. 70
52. In a mining machine, the combination with a supporting frame, of loop chain core cutting mechanism having an unobstructed core opening therethrough and mounted on said frame for rotation on a substantially horizontal axis, means for operating said cutting mechanism including upward swing thereof to cut a solid core of material in a mine wall toward the roof of a mine chamber, and mechanism mounted on said frame for adjusting the height of said horizontal axis relatively to said frame. 75
53. In a mining machine, the combination with a supporting frame, of loop chain core cutting mechanism having an unobstructed core opening therethrough and mounted on said frame to swing on an axis extending in a general horizontal direction, of means for operating said core cutting mechanism including swinging feeding movement thereof relatively to said frame, and mechanism for holding the cutting mechanism in adjusted position as to radial length in approximately the plane of said cutting mechanism. 80
54. In a mining machine, the combination with a supporting frame, of core cutting mechanism mounted on said frame for arcuate reciprocation between the floor and roof of a mine chamber for cutting a core of material in a mine wall in advance of said frame, means for operating said cutting mechanism to cut a core of material in a mine wall in advance of said frame from the floor to the roof of the mine chamber and mechanism assisted by the weight of the severed core for returning the cutting mechanism toward initial position in a direction reverse to the feeding direction. 85
55. In a mining machine, the combination with a main frame, of forwardly projecting arms, a loop chain cutter suspended from the outer ends of said arms on a horizontal axis of rotation, means for moving said loop chain cutter on said horizontal axis semi-cylindrically, and means for moving the severed section of material circumferentially toward loading position. 90
56. In a mining machine, the combination with a loop chain cutter comprising a frame having an unobstructed receiving opening extending therethrough and cutting devices carried by the forward face of said frame, of a horizontal axial pivotal support for said loop chain cutter, and means for adjusting the height of said axial support. 95
57. In a mining machine, the combination with loop chain core cutting mechanism having an unobstructed core opening therethrough, of a supporting frame, means for 100
- 105
- 110
- 115
- 120
- 125
- 130

- suspending said cutting mechanism on a horizontal axis from the forward portion of said supporting frame for operation on an upright mine wall in advance of said frame, 5 means for actuating said cutting mechanism, and rope gearing for swinging the cutting mechanism during the actuation thereof to cut a core of material in the upright mine wall in advance of said frame.
- 10 58. In a mining machine, the combination with a supporting frame, of cutting mechanism mounted thereon for operation in advance thereof, means for operating said cutting mechanism including upward arcuate feed thereof along an upright mine wall to sever an upright crescent shaped section of material from the mine wall, and loading apparatus mounted on said frame for moving said section of severed material back 15 from the mine wall along the reverse line of movement of said cutting mechanism.
59. In a mining machine, the combination with a supporting frame, of core cutting mechanism mounted thereon on a horizontal 20 axis for movement relatively thereto in advance of said frame, of means for operating said cutting mechanism to sever a section of material from a mine wall adjacent said frame, and flexible means connected to said 25 cutting mechanism to follow the same for engaging the severed section of material and moving the same back from the mine wall.
60. In a mining machine, the combination with a supporting frame, of core cutting 30 mechanism having an unobstructed core opening therethrough for the passage of material cut thereby, said cutting mechanism being pivotally mounted on said frame for arcuate movement relative thereto on a horizontal axis, means for operating said core cutting mechanism including arcuate feed thereof relative to said frame on such horizontal axis to cut a solid upright core of material from a mine wall adjacent said 35 frame, and power operated mechanism under the control of the operator, for moving the severed material back from the mine wall in a direction reverse to such feeding direction to effect the transfer of the cut material 40 along said frame toward loading position.
61. In a mining machine, the combination with a main frame, of a loop chain cutter suspended on a horizontal axis therefrom in a U-shaped frame, the latter having an unobstructed core opening therethrough, means 45 for actuating said cutter, apparatus for swinging said loop chain cutter and its frame forwardly and upwardly on such horizontal axis to sever a core of material from a mine wall, and mechanism mounted on said main frame and connected to said U-shaped frame to move the core of material back from the 50 mine wall.
62. In a mining machine, the combination 55 with loop chain core cutting mechanism for

producing a U-shaped kerf in a mine wall, of means for operating said core cutting mechanism including swinging feed thereof vertically through approximately 180° on an axis extending in a general horizontal 70 direction, and adjusting mechanism for varying the radial length of said core cutting mechanism.

63. In a mining machine, the combination with a main frame, of a supplemental frame, 75 a chain cutter frame pivotally suspended from said supplemental frame on a transverse axis extending in a general horizontal direction, an endless chain cutter mounted on said chain cutter frame in a plane extending transversely of said main and supplemental frames, the cutters of said chain cutter extending forwardly when in initial position, means for actuating said chain cutter by causing the same to travel along said chain cutter frame, means for feeding said chain cutter by swinging said chain cutter frame forwardly and upwardly to produce a U-shaped kerf and a vertical crescent shaped section of material in a mine wall 90 in advance of said main and supplemental frames, and means on said main frame extending into position for moving the dislodged material back from the mine wall toward loading position in a general horizontal 95 direction along said main frame.

64. In a mining machine, the combination with framework, of a U-shaped kerf cutting device mounted on said framework to swing on a horizontal axis and having its cutters 100 extending forwardly when in initial position, means for operating said kerf cutting device to produce a substantially U-shaped kerf and an upright crescent shaped core of material in a mine wall, and loading apparatus mounted on said framework and extending into position for moving back from the mine wall in a general horizontal direction the material dislodged by the production of said U-shaped kerf. 105

65. In a mining machine, the combination with a supporting frame, of a loop chain core cutter pivotally supported on said frame on an axis extending transversely of said frame, and means for operating said loop chain core cutter including feed thereof in an upwardly extending arc, to cut an upright core in the mine wall adjacent said frame. 110

66. In a mining machine, the combination with a main frame, of a supplemental frame movable relatively thereto, loop chain core cutting mechanism pivotally supported by said supplemental frame on a substantially horizontal axis, means for operating 120 said loop chain core cutting mechanism including arcuate feed thereof, from a position below such horizontal axis, forwardly and upwardly to a position above said horizontal axis, and mechanism connected between 125 130

said main and supplemental frames for adjustably holding the supplemental frame and said loop chain core cutting mechanism between the floor and roof of the mine 5 chamber.

67. In a mining machine, the combination with a main frame, of a supplemental frame movable relatively thereto, loop chain core cutting mechanism supported by said 10 supplemental frame for swinging movement on a horizontal axis, a prime mover on said main frame, flexible connections between said prime mover and said loop chain core cutting mechanism for operating the latter 15 including arcuate feed thereof relatively to said main frame on such horizontal axis, and means for adjusting the position of said supplemental frame relatively to said main frame and holding said supplemental 20 frame in adjusted position without interfering with the operativeness of said flexible connections.

68. The combination with a main frame, of a supplemental frame pivoted thereto on 25 a horizontal axis, loop chain core cutting mechanism carried by said supplemental frame, a bracing member pivoted to said main frame, a screw threaded rod pivoted to said supplemental frame, and means co- 30 acting with said pivoted bracing member and said pivoted rod to adjust the position of said supplemental frame in elevation and hold the same in adjusted position.

69. The combination with a loop chain 35 cutter, of a frame having an unobstructed core opening therethrough, and supporting and guiding said chain cutter, said frame being of such narrow dimension as to enter the kerf produced by said chain cutter, 40 means for operating said chain cutter, and means for slowly feeding said chain cutter on a horizontal axis of rotation to cause said chain cutter to produce a U-shaped kerf in a mine wall and cut an up- 45 right crescent-shaped block of material therefrom.

70. The combination with frame-work, of 50 loop chain core cutting mechanism suspended therefrom to swing on a substantially horizontal axis of rotation, a rope connected to said loop chain core cutting mechanism, and means for exerting a pull on said rope to effect the swinging of said loop chain core cutting mechanism.

55 71. In a mining machine, the combination with a main frame, of a supplemental frame connected thereto, loop chain core cutting mechanism suspended from said supplemental frame to swing on a substantially horizontal axis, means for adjusting 60 said supplemental frame to vary the height of said horizontal axis, a rope guide fixed to said loop chain core cutting mechanism, a rope associated with said rope guide and 65 connected to said loop chain core cutting

mechanism, and means for exerting a pull on said rope to swing said loop chain core cutting mechanism in feeding direction.

72. In a mining machine, the combination with a supporting frame, of loop chain core 70 cutting mechanism mounted on the forward end of said frame to swing on a horizontal axis, means for operating said loop chain core cutting mechanism to cut an upright crescent shaped core in a mine wall in advance of said frame, flexible mechanism adapted to move along the kerf back of the core of material, and means for exerting a pull on the rear end of said flexible mechanism to move the same back and restore said 75 core cutting mechanism to initial position.

73. In a mining machine, the combination with a supporting frame, of core cutting mechanism mounted on the forward end of said frame to swing on a horizontal axis, 80 means for operating said core cutting mechanism to cut an upright crescent shaped core in a mine wall in advance of said frame, flexible mechanism connected at its forward end to said core cutting mechanism, and 85 movable with said core cutting mechanism along the kerf back of the core of material, a chute back of said core cutting mechanism and extending from the forward portion of said frame toward the rear, and means for 90 exerting a pull on the other end of said flexible mechanism to restore said cutting mechanism to initiate position and move the core 95 of material along said chute toward loading position.

74. In a mining and loading machine, the combination with a frame comprising a chute open at both ends, of an endless conveyer mounted on said frame in position to travel along said chute to carry material 100 from the forward portion of said chute to the rear end thereof, a reciprocable carrier movable back and forth along said chute for delivering material to said endless conveyer, means for dislodging material from a mine 105 wall in advance of said frame, and means for operating said carrier for receiving the dislodged material directly from its cut position in the mine wall and for transferring such material into the forward open end of 110 said chute for delivery to said endless conveyer to be transferred by the latter to the rear end of said chute.

75. In a mining and loading machine, the combination with a frame comprising a 115 longitudinal chute inclined toward the mine floor at its forward portion and extending on an upward incline to the rear end of said frame, of loop chain core cutting mechanism having an unobstructed core opening therethrough, and mounted on a horizontal axis at the forward end of said frame, means for operating said loop chain core cutting mechanism including upward feed thereof to cut a crescent shaped core of material in a mine 120

125

- wall in advance of said frame, a flexible core carrier comprising a plurality of spaced apart ropes connected at their forward ends to the core cutting mechanism and movable 5 with the latter back of the core cut in the mine wall, means for supporting said ropes in spaced apart relation along the upper surface of said chute and from the front to the rear thereof, and means mounted on said 10 frame for exerting a pull on said core carrier to restore the core cutting mechanism to initial position and move the core from the mine wall into said inclined chute toward loading position.
- 15 76. In a mining and loading machine, the combination with a supporting frame, having a chute mounted thereon, of core cutting mechanism mounted at the forward portion of said frame to swing on a horizontal 20 transverse axis for operating in advance thereof and in advance of said chute, and mechanism adapted to receive the cut material and transfer it along said chute to the rear portion thereof.
- 25 77. In a mining and loading machine, the combination with a frame having a chute extending longitudinally thereof, of dislodging mechanism mounted on said frame for operation in advance thereof, mechanism 30 adapted to extend between the forward open end of said chute and the mine wall for receiving the material as it becomes detached from the mine wall in large blocks, and means for reciprocating said receiving 35 mechanism to transfer the dislodged material along said chute toward loading position and return forwardly along said chute to receiving position for another load.
78. In a mining and loading machine, the 40 combination with a supporting frame having a chute extending longitudinally thereof and inclined forwardly to the mine floor and extending rearwardly toward loading position, of loop chain core cutting mechanism mounted on said frame to swing forwardly in advance of said frame and in advance of said chute on a horizontal axis, means for operating said loop chain core cutting mechanism to cut an upright crescent shaped core in the mine wall in advance of said frame, a flexible carrier adapted to extend between the forward open end of said chute and the rear surface of said core in position to receive the latter when 50 dislodged, means for operating said flexible carrier to transfer the dislodged core along said chute toward loading position, and means for reversing the movement of said flexible carrier along said chute back to its 55 receiving position in advance of said chute.
- 60 79. In a mining and loading machine, the combination with a supporting frame, of core cutting mechanism mounted thereon to swing on a horizontal transverse axis, means

for operating said core cutting mechanism 65 including swinging feeding movement on such axis to sever a section of material from a mine wall adjacent said frame, a flexible member connected to said core cutting mechanism and entering the mine wall therewith, mechanism for operating said flexible member to cause the same to move the severed section of material back from the mine wall, and a conveyer separate and independent of said flexible member for 70 operation but in position to continue the movement of the severed material to loading position.

80. In a mining and loading machine, the combination with a supporting frame, of an inclined runway on said frame, loop chain core cutting mechanism mounted on a horizontal transverse axis at the forward end of said runway, operating mechanism mounted on said frame, a cable extending 85 from said operating mechanism to said cutting mechanism for swinging the latter on such horizontal axis to feed the same, and a cable extending from said operating mechanism to said cutting mechanism for 90 restoring the latter.

81. A mining machine adapted to cut cores of material in a mine wall between the floor and roof thereof, comprising a main frame, a supplemental frame pivoted 95 at one end on a horizontal axis to said main frame, core cutting mechanism having an unobstructed core opening therethrough and rotatably mounted on a horizontal axis at the other end of said supplemental frame 100 for swinging movement relatively to said supplemental frame, and a rigid adjustable brace for holding said supplemental frame in adjusted position against movement either back or forth during the operation of said core cutting mechanism including swinging feed thereof.

82. In a mining machine, the combination with a supporting frame, of a supplemental frame, core cutting mechanism suspended 110 from said supplemental frame to swing on a substantially horizontal axis between the floor and roof of a mine chamber, mechanism for adjusting said supplemental frame to center such horizontal axis between the 115 floor and roof of the mine chamber, and means for operating said core cutting mechanism to cut in one feeding movement an upright crescent shaped core in the mine wall adjacent said frame.

83. In a mining and loading machine, the combination with a supporting frame, of loop chain core cutting mechanism suspended from the forward portion of said frame for swinging movement on a horizontal axis in an upward direction in advance of said frame, means for operating said loop chain core cutting mechanism in-

cluding feed thereof to cut an upright crescent shaped core in the mine wall in advance of said frame, flexible receiving mechanism connected to said loop chain core cutting mechanism to move therewith into the mine wall back of the core of material, a chute on said frame inclined downwardly toward the forward portion of said frame in position for receiving the core of material from a mine wall, means for mounting said flexible receiving mechanism on said frame to extend upwardly along said chute, means for operating said flexible receiving mechanism to transfer the core of material from the mine wall into the forward receiving end of said chute and upwardly along the latter toward loading position, and mechanism mounted in said chute for preventing said core of material from moving backward toward the receiving end of said chute, but permitting free movement of said material upwardly along said chute.

84. In a mining and loading machine, the combination with a supporting frame, of an inclined platform mounted thereon, core cutting mechanism mounted on the forward end of said frame to swing on a horizontal axis, means for operating said core cutting mechanism to cut an upright core in the mine wall in advance of said frame, flexible receiving means connected to said core cutting mechanism and extending rearwardly therefrom along said inclined platform, means for operating said flexible receiving means to deliver dislodged material from the mine wall to said inclined platform, and a plurality of spaced apart spring pressed pawls for preventing retrograde movement of the material moved onto said platform, but permitting free movement of such material upwardly along said platform.

85. A mining machine, comprising an upright framework; a cutter head rotatable about a horizontal axis and supported by said framework for vertical adjustment thereon; a loop cutter carried by said cutter head and having an unobstructed core-opening therethrough; and means for shifting said cutter head and cutter relative to said axis of rotation.

86. A mining machine, comprising an upright supporting framework; brackets secured to said framework; supporting members journaled in said brackets for rotation about a common axis; and a core-cutter carried by said supporting members and rotatable therewith and adjustable thereon relative to said axis of rotation.

87. A mining machine, comprising a supporting framework; brackets carried by said framework for vertical adjustment thereon; supporting members journaled in said brackets for rotation about a horizon-

tal axis; and a core cutter carried by said supporting members for rotation therewith and for adjustment thereon relative to said axis of rotation.

88. In a mining machine, the combination with a supporting frame, of core-cutting mechanism having an unobstructed core opening therethrough and mounted on said frame for arcuate movement between the floor and roof of a mine chamber on a substantially horizontal axis, and means for varying the effective radius of said core-cutting mechanism relatively to said axis.

89. In a mining machine, the combination with core-cutting apparatus fed on a horizontal axis, of a sling comprising a plurality of ropes connected to said core-cutting apparatus, a drum for said ropes, and means for effecting the winding of said ropes on said drum so that the dislodged material is withdrawn by said sling.

90. In a mining machine, the combination with a supporting frame, of core-cutting mechanism having an obstructed core-opening therethrough and carried by said frame for arcuate feed about a horizontal axis of swinging movement, means for adjusting the core-cutting mechanism bodily to vary the elevation of said axis on said frame, and means for operating said core-cutting mechanism including arcuate feed thereof on said axis in its adjusted position.

91. In a mining machine, the combination with a supporting frame, of a loop chain core-cutter having an unobstructed core-opening therethrough and mounted for swinging feeding movement on said supporting frame on a substantially horizontal axis, a sling connected to the outer end of said loop chain core-cutter to move upwardly therewith and back of the core of material cut, and means for operating said sling to transfer material of the core toward loading position.

92. In a mining machine, the combination with a supporting frame, of a core-cutter having an unobstructed core-opening therethrough and mounted on said frame for arcuate feeding movement on a substantially horizontal axis, a rope drum mounted on said frame for rotation on an axis substantially parallel with the axis of arcuate feeding movement of said cutter, a sling having one end secured to said core-cutter and the other end connected to said drum and arranged to be drawn by said core-cutter into the kerf formed thereby during the severing operation of said cutter, and means for operating said drum to wind said sling thereon to transfer the material of the core from its severed position and away from the mine wall.

93. In a mining machine, the combination with a supporting frame, of loop chain core-

cutting mechanism having an unobstructed core-opening therethrough mounted on one side of said frame for upright arcuate movement on a substantially horizontal axis, a 5 rope drum mounted on the opposite and rear side of said frame at the lower portion thereof for rotation on a substantially horizontal axis parallel to the axis of feeding movement of said core-cutting mechanism, 10 a plurality of spaced-apart ropes connected to the outer end of said loop chain core-cutting mechanism to move therewith back of the core of material cut by said core-cutting mechanism, said ropes being also connected to said rope drum and wound thereon, and means for operating said rope drum to simultaneously exert pulls on all of said ropes to transfer the material of the core from the mine wall in front of said frame 15 to the other side of said frame while restoring said core-cutting mechanism to initial position.

94. In a mining machine, the combination with a supporting frame, of cutting mechanism mounted thereon for producing a U-shaped kerf in a mine wall, means for swinging said cutting mechanism upwardly on a horizontal axis above the same, and adjusting mechanism for varying the radial 30 length of said kerf-cutting mechanism.

95. In a mining machine, the combination with a main frame, of a supplemental frame movable relatively thereto, core cutting mechanism having an unobstructed core opening 35 therethrough and supported by said supplemental frame to swing on a horizontal axis, and means connected between said main and supplemental frames for bracing the latter while said horizontal axis is held in adjusted elevation.

96. In a mining machine, the combination with a main frame, of a supplemental frame movable relatively thereto, core-cutting mechanism having an unobstructed core-opening therethrough and supported by said supplemental frame on a transverse axis, means for adjusting the position of said supplemental frame relatively to said main frame and holding said supplemental frame 45 in adjusted position to effect the adjustment of elevation of said transverse axis, and means for operating said core-cutting mechanism including forward and upward feeding movement on said transverse axis to cut an upright core in a mine wall in advance of said main and supplemental frames.

97. In a mining machine, the combination with supporting framework, of core-cutting mechanism having an unobstructed core-opening therethrough and suspended on a transverse horizontal axis from said supporting framework, means for actuating said core-cutting mechanism, and a rope drive for swinging said core-cutting mechanism 60 to effect feeding movement thereof on said

axis during the actuation of said cutting mechanism to cut an upright core in a mine wall.

98. In a mining machine, the combination with a main frame, of a supplemental frame 70 movably mounted on said main frame, core-cutting mechanism having an unobstructed core-opening therethrough and mounted on said supplemental frame to swing on a horizontal transverse axis, means for holding said supplemental frame in predetermined relation to said main frame to hold said transverse axis at adjusted elevations, means for actuating said core-cutting mechanism, and rope drive mechanism mounted on said 75 main frame and extending to said kerf-cutting mechanism to swing the latter on said transverse axis irrespective of the elevation of the latter to effect swinging feeding movement of said core-cutting mechanism during 80 the actuation of the latter.

99. The combination with core-cutting mechanism having an unobstructed core-opening therethrough, of means for operating the same, a frame for carrying said 90 cutting mechanism, a pivotal support for said frame, a segmental plate connected to said frame to oscillate therewith, a rope associated with said segmental plate and said frame, and means for exerting a pull on said 95 rope to effect feeding of said cutting mechanism during operation.

100. A mining machine comprising a loop chain cutter, a stirrup having an unobstructed core-opening therethrough and arranged 100 to carry said chain cutter, a swinging support for carrying said stirrup on a transverse horizontal axis, means for adjustably holding said swinging support in predetermined positions, means for actuating said 105 chain cutter, and means for swinging said stirrup on said transverse axis at the adjusted elevation of the latter to effect forward and upward feeding movement of said chain cutter to cut an upwardly extending 110 core in a mine wall in advance of said swinging support.

101. A mining machine comprising a frame having forwardly projecting arms, a shaft carried by said arms so as to be transverse to the longitudinal and vertical axes of said frame, a swinging frame carried by said shaft, a chain cutter, means for driving said chain cutter, a chain cutter frame movable relatively to said swinging frame, means for 115 adjustably securing said chain cutter frame to said swinging frame, a driving sprocket carried by said swinging frame, means for operating said sprocket, and means for guiding said chain cutter.

102. A mining machine comprising cutting mechanism, rope gearing for effecting feeding of said cutting mechanism, winding apparatus comprising reduction gearing for slowly operating said rope gearing during 120

feeding operation, loading apparatus connected to said rope gearing, means for operating said loading apparatus, direct gearing associated with said winding apparatus, and means for connecting said direct gearing in place of said reduction gearing to effect quick restoration of said loading apparatus to initial position.

103. In a mining machine, the combination with core-cutting mechanism, of a main frame, a supplemental frame movable relatively to said main frame and pivotally supporting said core-cutting mechanism, power mechanism mounted on the rear of said main frame, and flexible power transmitting mechanism between said power mechanism and said core-cutting mechanism.

104. In a mining machine, the combination with a main frame, of a supplemental frame pivoted thereto, cutting mechanism pivoted to said supplemental frame on a substantially horizontal transverse axis, said cutting mechanism having an unobstructed core-opening therethrough, means for holding said supplemental frame in adjusted position and said horizontal axis at adjusted elevation, power mechanism mounted on said main frame, a sprocket chain connection between said power mechanism and said cutting mechanism to effect the driving of said cutting mechanism, and means for swinging said cutting mechanism on said horizontal transverse axis to effect feeding movement of said cutting mechanism during the driving thereof to cut a core in a mine wall in advance of said frames.

105. In a mining machine, the combination with a main frame, of a supplemental frame pivoted thereto, loop chain core-cutting mechanism having an unobstructed core-opening therethrough and pivotally suspended from said supplemental frame, means for holding the supplemental frame with said cutting mechanism in adjusted position relatively to said main frame, power mechanism mounted on the rear portion of said main frame, and a flexible driving connection between said power mechanism and said cutting mechanism.

106. In a mining machine, the combination with a supporting frame, of loop chain core-cutting mechanism having an unobstructed core-opening therethrough and mounted to swing on a horizontal axis on said frame in position for cutting an upright core in a mine wall, means for operating said loop chain core-cutting mechanism including swinging feeding movement thereof on an axis having a fixed relation to said supporting frame, means for restoring said core-cutting mechanism to approximately initial position, a motor mounted on said main frame, and power transmitting mechanism connected between said motor and said operating means and also said re-

storing means whereby said motor is common to both said operating means and said restoring means.

107. In a mining machine, the combination with a supporting frame, of a loop chain core-cutter having an unobstructed core-opening therethrough and mounted on said supporting frame in position to cut a U-shaped kerf in a mine wall to form an upright crescent-shaped block of material therefrom, and means for operating said chain cutter including swinging feeding movement thereof on a horizontal axis at the forward end of said supporting frame.

108. In a mining and loading machine, the combination with a supporting frame comprising a passageway for dislodged material, of core-cutting mechanism for dislodging material from a mine wall in advance of said frame, a reciprocating conveyor movable back and forth from a position at the forward portion of said passageway, and means for operating said conveyor for receiving the dislodged material directly from its position at the mine wall and transferring such material toward the rear end of said passageway.

109. In a mining and loading machine, the combination with a supporting frame comprising an inclined chute, of means for dislodging material from a mine wall in advance of said frame and near the forward end of said chute on the floor of the mine chamber, and means for receiving the dislodged material from its native position in the mine wall and transferring such material over the floor of the mine chamber and along said chute toward loading position.

110. In a mining and loading machine, the combination with a frame having an inclined chute with its forward end and its rearward end open and its forward end extending to a position at the mine floor, of mechanism for dislodging material from a mine wall for movement into the forward open end of said chute at the mine floor, and reciprocating mechanism mounted on said frame in position to transfer material along said chute toward loading position.

111. In a mining and loading machine, the combination with a frame having a chute extending longitudinally thereof, of core-cutting mechanism having an unobstructed core-opening therethrough and mounted on said frame for operation in advance thereof, mechanism adapted to extend between the forward open end of said chute and the mine wall for receiving the material as it becomes detached from the mine wall in large blocks, and means for reciprocating said receiving means to transfer the dislodged material along said chute toward loading position and return forwardly along said chute to receiving position for another load.

112. In a mining machine, the combination with a main frame, of a supplemental frame movable relatively thereto, core-cutting mechanism having an unobstructed 5 core-opening therethrough and pivotally connected to said supplemental frame on a horizontal axis for swinging feeding movement, and means connected between said main and supplemental frames for bracing 10 the latter and holding said pivotal connection between said core-cutting mechanism and said supplemental frame in adjusted position in accordance with a predetermined swinging path of travel of said core-cutting mechanism. 15
113. In a mining machine, the combination with a supporting frame, of cutting mechanism mounted thereon in position to cut initially in a substantially horizontal 20 direction followed by an upward direction from a horizontal kerf, and means for operating said cutting mechanism to cut a pair of separated side kerfs and a back kerf connecting said side kerfs, said operating 25 means including means for feeding the cutters in an upward direction during the cutting operation whereby a depending pillar of material is formed. 30
114. In a mining machine, the combination with a supporting frame, of kerf-cutting mechanism mounted on said supporting frame in position to cut a kerf in a substantially horizontal direction along the floor of the mine chamber and also for cutting 35 in an upward direction from the horizontal kerf, means for driving said kerf-cutting mechanism, and means for feeding said kerf-cutting mechanism in an upward direction to cut a pair of separated side kerfs and a 40 back kerf connecting said side kerfs to form a depending pillar of material in a mine wall. 45
115. In a mining machine, the combination with a supporting frame, of kerf-cutting mechanism mounted thereon in position to cut a kerf in a substantially horizontal direction and also in an upward direction from the horizontal kerf, said kerf-cutting mechanism comprising an open frame of 50 such dimensions as to enter the upward kerfs, means for driving said kerf-cutting mechanism, and mechanism for feeding said kerf-cutting mechanism to cut a pair of separated side kerfs and a back kerf connecting said side kerfs but moving said open frame into the upward kerfs during the cutting operation to form a depending pillar of material extending through said open frame. 55
116. In a mining machine, the combination with a supporting frame, of kerf-cutting mechanism mounted thereon in position to cut a kerf along the floor of the mine chamber in a general horizontal direction 60 and also in an upward direction from such floor, said kerf cutting mechanism comprising an open frame of such dimensions as to be capable of entering the upward kerfs produced by said kerf-cutting mechanism, and means for operating said kerf-cutting mechanism including upward feed thereof to form a pair of separated side kerfs and a back kerf connecting said side kerfs around a depending pillar of material extending through said open frame. 65
117. In a mining machine, the combination with a supporting frame, of a cutter frame having an unobstructed core-opening therethrough and mounted on said supporting frame for movement in a general horizontal direction and in an upward direction, a single set of cutters carried by said cutter frame, means for driving said cutters relatively to said cutter frame, and means for feeding said cutter frame together with said cutters to effect kerf-cutting along the floor of the mine chamber initially and then in an upward direction to form separated side kerfs and a connecting back kerf around a depending pillar of material in a mine wall. 70
118. In a mining machine, the combination with a supporting frame, of kerf-cutting mechanism mounted thereon to cut a kerf in a general horizontal direction and to cut in an upward direction from such horizontal kerf to form a pair of side kerfs and a back kerf enclosing a pillar of material in a mine wall, and removing means mounted on said supporting frame in position to catch and carry off dislodged material. 75
119. In a mining machine, the combination with a supporting frame, of kerf-cutting mechanism mounted thereon in position to cut a kerf in a general horizontal direction and in an upward direction from the horizontal kerf by cutting a pair of side kerfs and a back kerf enclosing a depending pillar of material, and removing means arranged in relation to the horizontal kerf in position on said frame to receive and transfer dislodged material toward loading position. 80
120. In a mining machine, the combination with a supporting frame, of a cutter frame having an unobstructed core-opening therethrough and mounted on said supporting frame for movement relatively thereto, a single set of cutters mounted on said cutter frame in position for cutting a kerf into which a portion of said cutter frame may enter in a general horizontal direction, means for driving said cutters relatively to said cutter frame, means for moving said cutter frame relatively to said supporting frame to feed said cutters in an upward direction to form a core extending through the space enclosed by said cutter frame, and loading apparatus extending into the hori- 85

- 125

zontal kerf beneath the core of material for receiving dislodged material and moving the same toward loading position.

121. In a mining machine, the combination with a supporting frame, of a cutter frame having an unobstructed core-opening therethrough and pivoted to said supporting frame to swing about an axis transverse to the vertical and longitudinal axes of the machine, a cutter chain carried by said cutter frame to travel along the latter, and means for operating the cutting mechanism by driving said cutter chain while swinging said cutter frame to cut forward and upward.

122. In a mining machine, the combination with a supporting frame, of a cutter frame having an unobstructed core-opening therethrough and pivoted to said supporting frame to swing about an axis transverse to the vertical and longitudinal axes of the machine, an endless chain cutter mounted on said cutter frame, means for driving said endless chain cutter relatively to said cutter frame, and means for swinging said cutter frame to feed said chain cutter while being driven to effect the cutting of a kerf in the general direction of the floor of the mine chamber and also upwardly to form separated side kerfs and a connecting back kerf enclosing a depending core of material in an upright mine wall.

123. In a mining and loading machine, the combination with a supporting frame, of cutting mechanism mounted on said supporting frame in fixed relation thereto, means for operating said cutting mechanism, including swinging feeding movement thereof and at the same time extending said conveying mechanism under the cut material, and means for operating said conveying mechanism to transfer the cut material toward loading position.

124. In a mining and loading machine, the combination with a supporting frame, of cutting mechanism mounted thereon, of means for operating said cutting mechanism, and conveyer mechanism movable to positions back of the forward end of said frame and extensible beyond the forward end of said frame under the cut body of material to collect dislodged material and transfer the same toward loading position.

125. In a mining and loading machine, the combination with a supporting frame, of core-cutting mechanism having an unobstructed core-opening therethrough and mounted on said frame to have a swinging feeding movement on a horizontal axis, and conveyer mechanism adapted to be extended beyond the forward end of said frame under the core of material to collect the latter and transfer the same toward loading position.

126. In a mining and loading machine, the combination with a supporting frame, of

kerf-cutting mechanism mounted thereon, means for operating said kerf-cutting mechanism, and loading apparatus comprising a chute and flexible means extensible beyond the forward end of said chute along the kerf 70 cut by said kerf-cutting mechanism to collect the cut material and transfer the same along said chute toward loading position.

127. The combination of a bodily movable cutting mechanism for entirely severing a 75 block of coal from the vein, means for afterward moving said cutting mechanism to remove the whole block intact which it has severed, and an upwardly inclined chute disposed in registry with the movement of 80 said cutting mechanism and into which the cutting mechanism discharges said block.

128. The combination of a bodily movable cutting mechanism for entirely severing a 85 block of coal from the vein, means for afterward moving said cutting mechanism to remove the whole block intact which it has severed, an upwardly inclined chute disposed in registry with the movement of said cutting mechanism and into which the cutting mechanism discharges said block, and means for holding said severed block in 90 position to be moved along the chute by the next set of blocks.

129. The combination of a bodily movable cutting mechanism for entirely severing a 95 block of coal from the vein, means for moving said cutting mechanism to remove the whole block intact which it has severed, a chute disposed in the line of 100 movement of said cutting mechanism and into which the cutting mechanism discharges said block, means for holding said severed block in position to be moved along the chute by the next set of blocks, and 105 means operated by said bodily movable cutting mechanism for clearing the chute of severed blocks.

130. The combination of an oscillating cutting mechanism adapted on its forward 110 stroke to entirely sever a block of coal from the vein, means operable on the return stroke of said cutting mechanism for removing the severed block in its entirety, a receiving structure disposed coincident with 115 the line of movement of said cutting mechanism for directing the blocks of coal beyond said cutting mechanism, and means for tentatively holding the last block severed by said cutting mechanism in position to be 120 moved along said receiving structure by the next severed block.

131. The combination of a frame structure, a guiding structure disposed on an arc and extending substantially from the forward to the rear end of said frame structure, a cutting mechanism operable adjacent the forward end of said guiding structure and bodily movable on an arc, the center of which is coincident with the center of the 125 130

- arc on which the guiding structure is disposed, said cutting mechanism operating on its forward stroke to sever a block of coal from the mass thereof, and means operable 5 on the return stroke of said cutting mechanism for removing the severed block and placing the severed block on said guiding structure in position to be shoved along said guiding structure by the next severed block.
- 10 132. The combination of a curved receiving structure, means for entirely severing a block of coal from the vein thereof, and means for tentatively holding said block in said receiving structure in position to be 15 pushed along said receiving structure by the next succeeding block.
133. The combination of bodily movable cutting mechanism adapted on its forward stroke to cut out a block of coal from the 20 vein, means operable on the return stroke of said cutting mechanism for removing the block which has been cut, and a stationary guiding structure alined with said cutting mechanism for directing the blocks of coal 25 away from the cutting mechanism.
134. In a mining machine, the combination with a supporting frame, of cutting mechanism mounted thereon, means for operating said cutting mechanism including 30 bodily movement thereof relative to said frame to sever a block of coal from a mine vein, and a device mounted on said frame in position to be moved relatively thereto under the block of coal to support the same 35 in its original position in the mine wall while it is being cut.
135. In a mining machine, the combination with a main frame, of a supplemental frame, core-cutting mechanism mounted on 40 said supplemental frame, means for adjusting the supplemental frame on said main frame together with said core-cutting mechanism on a longitudinal axis extending in a general horizontal direction to adjust 45 the position of the latter to cut either horizontally or at an inclination from the horizontal, and means for operating said core-cutting mechanism including feed thereof over an arcuate path of travel.
- 50 136. In a mining and loading machine, the combination with a frame having an inclined chute open at its forward end and at its rear end, of mechanism for dislodging material from a mine wall for movement 55 into the forward open end of said chute, and reciprocable mechanism mounted on said frame in position to transfer material along said chute toward loading position.
- 60 137. In a mining machine, the combination with a supporting frame, of core-cutting mechanism mounted thereon and having an unobstructed core-opening therethrough, and an ejector mounted on said frame for movement relatively thereto along 65 a path substantially parallel to the path of said core-cutting mechanism in position to act on the cut material to move the same from its position at the mine wall.
138. In a mining machine, the combination with a supporting frame, of a chute in 70 position on said frame to extend longitudinally thereof to receive a solid block of material directly from its position in the mine wall, and cutting mechanism mounted on said frame in position for cutting a core of material in the mine wall spaced from the open receiving end of said chute but in registry with said chute and directly in front of such receiving end of said chute.
139. In a mining machine, the combination with a supporting frame, of a receiving structure mounted thereon, core-cutting mechanism mounted at one end of said receiving structure, means for guiding said core-cutting mechanism along a path of 80 travel enclosing a space in registry with said chute, and means for operating said core-cutting mechanism including the feed thereof along such path of travel to cut a core of material in one feeding operation in a mine 85 wall in alinement with said chute.
140. In a mining machine, the combination with a supporting frame, of a receiving structure mounted thereon, core-cutting mechanism, means for guiding said core-cutting mechanism back and forth in approximate alinement with said receiving structure, means for operating said core-cutting mechanism to cut in one operation a core of material in a mine wall in registry 90 with said chute, and means for bodily moving said core-cutting mechanism relatively to said receiving structure in a direction opposite to the feeding direction.
141. A mining machine comprising a supporting frame, cutting mechanism, means for operating the same, mechanism for feeding said cutting mechanism, and means on said frame comprising a device freely movable in feeding direction but engaging the 100 cut material when said cutting mechanism moves or tends to move in reverse direction.
142. A mining and loading machine comprising a supporting frame, core-cutting mechanism mounted thereon, means for operating said core-cutting mechanism including arcuate feeding movement thereof relatively to said supporting frame, and means mounted on said frame in position to extend under the core cut by said cutting mechanism to receive the core and move it from the mine wall.
143. In a mining machine, the combination with a supporting frame, of a receiver connected to said supporting frame, and 115 adapted to occupy a curved position in a curved kerf, means for dislodging material from a mine wall onto said receiver, and a conveyer on said supporting frame in position for transferring toward loading pos- 120
- 125
- 130

tion material received thereby from said receiver.

144. In a mining machine, the combination with a supporting frame, of core-cutting mechanism mounted thereon and having an unobstructed core opening therethrough, of means for operating said core-cutting mechanism, and an ejector in position on said frame to act on the cut material 10 immediately after being cut and in the position assumed thereby after being cut, said ejector being mounted on said frame in position to reach the cut material along substantially the entire mass thereof.

145. In a mining machine, the combination with means for dislodging an upright arcuate core of material, of a receiver connected to said frame and adapted to extend forwardly therefrom, and means for moving 20 said receiver under said arcuate core into receiving position.

146. In a mining machine, the combination with a supporting frame, of kerf-cutting mechanism mounted thereon for arcuate feeding movement relatively to said supporting frame, a flexible receiver mounted on said frame in position to receive severed material directly from the mine wall, and means for exerting force on the rear 25 portion of said receiver for moving the forward portion thereof along the arcuate kerf made by said kerf-cutting mechanism.

147. In a mining machine, the combination with a supporting frame, of kerf-cutting mechanism mounted for swinging feeding movement on said supporting frame in position to cut a kerf extending forward, upwardly and arcuately into a mine wall from the base thereof, a receiver mounted 30 on said frame in position to extend forwardly from said frame into such arcuate kerf, and means for moving said receiver forwardly relatively to said supporting frame into said kerf under the cut material 40 to receive the latter as soon as dislodged.

148. In a mining machine, the combination with a supporting frame, of kerf-cutting mechanism mounted on said frame for arcuate feeding movement relatively thereto, means 50 for operating said kerf-cutting mechanism including arcuate feed thereof to cut an arcuate kerf in a mine wall, a receiver mounted on said frame and adapted to occupy an arcuate position, and means for moving said receiver arcuately into the arcuate kerf formed by said kerf-cutting mechanism for receiving the cut material.

149. In a mining machine, the combination with a supporting frame, of core-cutting mechanism mounted thereon and having an unobstructed core opening therethrough, means for operating said core-cutting mechanism including arcuate feed thereof to cut an arcuate core in a mine wall, a receiver 60 mounted on said frame and adapted to oc-

cupy an arcuate position, and means for moving said receiver into arcuate position to receive dislodged core material.

150. In a mining machine, the combination with a supporting frame, of a chute 70 extending rearwardly from the forward end of said frame, core-cutting mechanism mounted on the forward end of said frame, means for operating said core-cutting mechanism to cut an upright crescent-shaped core 75 in advance of said frame, and mechanism for acting on the material in the position which it assumes after being cut and moving such material from the mine wall into said chute.

151. In a mining machine, the combination with a supporting frame, of a chute extending rearwardly along said frame on an upward incline from the lower forward end of said frame, core-cutting mechanism mounted for swinging movement on a substantially horizontal axis at the upper forward end of said frame, means for operating said core-cutting mechanism to cut an upright crescent-shaped core of material in a mine wall in advance of said frame, and 90 mechanism mounted on said frame in position to act on the cut material and move the same from the mine wall into said chute.

152. In a mining and loading machine, the combination with a supporting frame, of 95 means mounted thereon in position to dislodge material from an upright mine wall, a receiver mounted on said frame for movement relatively thereto in advance of said frame into position for receiving dislodged 100 material, means for projecting said receiver from said frame in advance thereof into receiving position, and means for retracting said receiver along said frame over substantially the same path traveled by said receiver 105 during its projecting movement into its advanced position.

153. In a mining machine, the combination with a supporting frame, of a cutter for forming an arcuate kerf in the material to be 110 mined, means for operating said cutter including arcuate feed thereof to cut such arcuate kerf, a receiver mounted on said frame and adapted to occupy an arcuate position as determined by said arcuate kerf, means for moving the receiver into position beneath the cut material, and conveyer mechanism for moving dislodged material toward loading position.

154. In a mining machine, the combination with a supporting frame, of a kerf cutter pivotally mounted on said frame, means for operating said kerf cutter including arcuate feed thereof to cut an arcuate kerf, a receiver adapted to occupy a curved 115 position as determined by said arcuate kerf, means for moving said receiver into said arcuate kerf, and conveyer mechanism cooperating with said receiver to transfer dislodged material toward loading position. 120 125 130

155. In a mining machine, the combination with a supporting frame, of a kerf cutter pivotally mounted thereon, means for operating said kerf cutter including arcuate feed thereof to form an arcuate kerf in a mine wall, a receiver connected to said supporting frame, means for moving said receiver into and out of the arcuate kerf formed by said kerf cutter, a conveyer 10 mounted on said supporting frame and having a receiving position adjacent said receiver, means for driving said conveyer for transferring toward loading position the material received thereby from said receiver, and means for maintaining operative connection between said conveyer and said driving means irrespective of the position of said receiver relative to said supporting frame.
156. In a mining machine, the combination with a supporting frame, of kerf-cutting mechanism mounted thereon, means for operating said kerf-cutting mechanism including arcuate feed thereof to form an arcuate kerf in the material to be mined, a receiver adapted to occupy a position having a radius of curvature approximately equal to the radius of curvature of a kerf formed by said kerf-cutting mechanism, and means 30 for moving said receiver into and out of said kerf.
157. In a mining machine, the combination with a supporting frame, of a conveyer extending longitudinally thereof from a forward receiving position near the forward lower end of said frame, core-cutting mechanism mounted on the upper forward end of said supporting frame, means for operating said core-cutting mechanism to cut an upper right crescent-shaped core of material in the mine wall in advance of said frame, and ejector mechanism for moving the cut material from the mine wall onto said conveyer.
158. The combination of a cutting mechanism for entirely severing a block of coal from the vein, means for bodily actuating said cutting mechanism to remove the severed block of coal while the latter remains intact, and a chute disposed in the line of movement of said cutting mechanism for receiving the block of coal from said cutting mechanism.
159. The combination of a bodily movable cutting mechanism for entirely severing a block of coal from the vein, means for afterward moving said cutting mechanism to remove the whole block intact which it has severed, and a chute disposed in the line of movement of said mechanism and 60 into which the cutting mechanism discharges said block.

160. The combination of kerf cutting mechanism having an unobstructed core-opening therethrough and bodily movable on a curved line for cutting out a block of

coal from the vein, means for removing said block of coal along said curved line, and means for tentatively holding the block in the path of the next succeeding block.

161. The combination of bodily movable cutting mechanism adapted on its forward stroke to cut a block of coal from the vein, means operable on the return stroke of said cutting mechanism for removing the block which has been cut, a relatively stationary receiving structure for directing the blocks of coal from said cutting mechanism, and means for tentatively holding said block of coal in said receiving structure at substantially the end of the return stroke of said cutting mechanism and in position to be shoved along said receiving structure by the succeeding block.

162. The combination of a loop-shaped cutting mechanism arranged to simultaneously cut a plurality of kerfs at an angle to each other to entirely sever a block of coal from the vein, means for bodily moving said cutting mechanism to remove the block of coal from its original relative position, and means for directing said block of coal away from the cutting mechanism.

163. The combination of a receiving chute, cutting mechanism operable near the end of said chute to entirely sever large blocks of material from the mine wall, means for insertion of the blocks successively in said chute as they are cut, and means for moving the blocks along the chute to clear the chute.

164. In a mining machine, the combination of a receiving chute, means for delivering blocks of material into said chute, and spring-pressed pawls for gripping blocks of material in said chute and preventing reverse movement thereof.

165. In a mining machine, the combination with a supporting frame, of a chute mounted thereon in position for receiving material directly from an upright mine wall, means for delivering material from the mine wall into the receiving end of said chute, and a yielding device permitting free movement of the solid material into said chute but holding the same from movement except toward the delivery end of said chute.

166. In a mining machine, the combination with a supporting frame, of cutting mechanism having an unobstructed core-opening therethrough for the passage of material cut thereby and mounted on a horizontal axis on said frame for feeding movement relatively thereto, of means for operating said core-cutting mechanism including feeding movement thereof on such horizontal axis and relatively to said frame for cutting an upright core in a mine wall adjacent said frame, and means mounted on said frame for moving a cut section of material in its entirety back from the mine

wall in a direction opposite to the direction of feeding travel of said core-cutting mechanism.

167. The combination with framework, of a kerf-cutting device mounted thereon, means for moving forwardly said kerf-cutting device on a horizontal axis and operating the same to produce a kerf in a mine wall, means for returning said kerf-cutting device to initial position, and automatic gripping means coacting with said returning means to move back from the mine wall the material dislodged. 10

168. In a mining machine, the combination with supporting framework, of a loop chain core-cutter having an unobstructed core-opening therethrough and supported by said framework in a plane extending transversely thereof, and means for operating said loop chain core-cutter including the feed thereof in an upwardly and forwardly extending arc relative to the longitudinal axis of the machine in advance of said framework. 15

169. In a mining machine, the combination with a supporting frame, of a loop chain core-cutter, a cutter frame having an unobstructed core-opening therethrough for supporting and guiding said chain cutter, and of such narrow dimensions as to enter the kerf produced by said chain cutter, means for actuating said chain cutter relatively to said cutter frame, and mechanism for slowly feeding said chain cutter forward on a transverse axis to cause said cutter to produce a U-shaped kerf in the mine wall in advance of said supporting frame and cut an upright core. 30

170. In a mining and loading machine, the combination with a supporting frame having a chute mounted thereon, of core-cutting mechanism mounted at the forward portion of said frame for operating in advance thereof and in advance of said chute to cut an upright core in a mine wall, and mechanism adapted to receive the cut material and transfer it along said chute to the rear portion thereof. 40

171. A mining machine comprising kerf-cutting mechanism, means for operating the same, and means freely movable in an upright arc into the kerf produced by said kerf-cutting mechanism and automatically engaging the cut material to remove the same from the mine wall upon reverse movement thereof. 50

172. In a mining machine, the combination with cutting mechanism, of means for operating said cutting mechanism to dislodge from a mine wall comparatively large blocks of material, flexible mechanism extending below the dislodged blocks of material for engaging and moving them from their native positions in the mine wall, and power trans- 60

mission means for actuating said material moving device.

173. In a mining and loading machine, the combination with a frame having an open-ended chute mounted thereon, of core-cutting mechanism mounted at the forward portion of said frame for operating in advance thereof and in advance of the forward open end of said chute to cut an upright core, and mechanism adapted to receive the cut material and carry it along said chute to the rear open end thereof. 70

174. In a mining machine, the combination with a main frame, of a supplemental frame movably mounted on said main frame, endless chain kerf cutting mechanism mounted on said supplemental frame for rotary adjustment relatively to said main frame, a bolt for locking said cutting mechanism in adjusted position, and means for operating said cutting mechanism from the axis of 80 such rotary adjustment.

175. In a mining machine, the combination with supporting framework, of a loop chain core-cutter having an unobstructed core-opening therethrough and supported by said framework in a plane extending transversely thereof to swing on a horizontal axis, and means for operating said loop chain core-cutter including the feed thereof in an upwardly extending arc in advance of said framework. 90

176. In a mining machine, the combination with a supporting frame, of a loop chain core-cutter, a cutter frame having an unobstructed core-opening therethrough for supporting and guiding said chain cutter and of such narrow dimensions as to enter the kerf produced by said chain cutter, means for actuating said chain cutter relatively to said cutter frame, and mechanism for slowly feeding said chain cutter forward on a transverse horizontal axis to cause said cutter to produce a U-shaped kerf in the mine wall in advance of said supporting frame and cut an upright core. 100

177. In a mine and loading machine, the combination with a supporting frame having a chute mounted thereon, of core-cutting mechanism mounted on a horizontal axis at the forward portion of said frame for operating in advance thereof and in advance of said chute to cut an upright core in a mine wall, and mechanism adapted to receive the cut material and transfer it along said chute to the rear portion thereof. 115

178. In a mining machine, the combination of mechanism for automatically cutting a solid core of material in a mine wall and automatically dislodging such core from the unmined mass, and means for lifting the core of material from the position it occupied in its native bed into a position from which it may be transported. 125

179. In a mining machine, the combination with a frame, of a chute mounted thereon, means for adjusting the position of said chute adjacent the mine wall, and means comprising an endless cutter with an unobstructed core opening extending therethrough for effecting the delivery of material from its position in the mine wall directly into said chute.
180. A mining and loading machine comprising a loop chain core-cutter, a frame for suspending said core-cutter in an upright plane, means for operating said chain cutter including upward feed thereof to cut an upright core of material from a mine wall, and means for moving back from the mine wall the section of material severed, while and after said chain cutter is restored to initial position.
181. The combination with a main frame, of a supplemental frame, a chain cutter frame pivotally suspended from said supplemental frame on a horizontal axis, an endless chain cutter mounted on said chain cutter frame in a plane extending transversely of said main and supplemental frames, the cutters of said chain cutter extending forwardly to produce a U-shaped kerf and a vertical crescent-shaped core of material in a mine wall when operated, and means in position on said main frame for moving back from the mine wall the dislodged material.
182. In a mining and loading machine, the combination with framework, of a U-shaped kerf-cutting device swingable on a horizontal axis and having its cutters extending forwardly when in initial position, means for operating said kerf-cutting device to produce a substantially U-shaped kerf and an upright crescent-shaped core of material in a mine wall, and loading apparatus on said framework in position for moving back from the mine wall the material dislodged by the production of said U-shaped kerf.
183. In a mining machine, the combination with framework, of kerf-cutting mechanism having an unobstructed core opening and pivotally suspended on said framework on the horizontal axis above said unobstructed core opening when said kerf-cutting mechanism is in initial position, means for operating said kerf-cutting mechanism including forward swinging feeding movement on said horizontal axis to cut an upright core in a mine wall in advance of said framework, means for returning said kerf-cutting mechanism to initial position, and automatic gripping means coacting with said returning means to move back from the mine wall the material dislodged.
184. A mining machine, comprising cutting mechanism, means for operating the same, feeding apparatus for said cutting mechanism, and means moving freely in an upright arc in the feeding direction for engaging cut material in its cut position in the mine wall upon reverse movement of said means.
185. A mining machine comprising a supporting frame, kerf-cutting mechanism mounted on said frame for swinging feeding movement in an upright arc, and means movable along said upright arcuate kerf freely in one direction and operating to engage the material cut by said cutting mechanism upon the reverse movement thereof.
186. A loop chain cutter, a U-shaped frame for said chain cutter, a swinging frame, supporting mechanism for said swinging frame on a horizontal axis, means for adjustably securing the legs of said U-shaped frame to said swinging frame to enable the radial length of said loop chain cutter to be varied, mechanism for operating said chain cutter, and apparatus for swinging the chain cutter frame to feed the chain cutter during the cutting operation.
187. A mining machine comprising a loop chain cutter, a U-shaped frame therefor, a swinging frame, a shaft for supporting said swinging frame, means for adjustably securing the legs of said U-shaped frame to said swinging frame to project above said shaft when said chain cutter is in initial position, a supporting frame for said shaft comprising forwardly extending arms of such length as to give freedom of movement of the ends of said U-shaped frame throughout approximately a semi-circle, means for operating said chain cutter, and apparatus for feeding the same during operation.
188. A loop chain core-cutter having an unobstructed core opening therethrough, a frame therefor, means for operating said chain cutter, feeding mechanism for said frame and chain cutter, a plate supported by said frame, and a guide for said chain at one end of said plate, the other end of said plate being supported adjacent said chain cutter operating means.
189. In a mining machine, the combination with a supporting frame, of kerf-cutting mechanism mounted on said frame to have an upward swinging feeding movement on a substantially horizontal transverse axis, means for operating said kerf-cutting mechanism including feeding movement thereof on such horizontal transverse axis, means connected to said kerf-cutting mechanism and movable freely in the feeding direction along the kerf produced by said kerf-cutting mechanism, and mechanism for moving said last-named means in the opposite direction to cause the same to act on the cut material to dislodge the latter.
190. In a mining machine, the combina-

- tion with kerf-cutting mechanism comprising a cutter frame, of means for supporting said kerf-cutting mechanism for swinging feeding movement on a horizontal axis, means 5 for operating said kerf-cutting mechanism including feeding movement thereof on such horizontal axis, restoring mechanism connected to said cutter frame and movable therewith into the kerf produced thereby, 10 and mechanism movable freely with said restoring mechanism in the feeding direction of said kerf-cutting mechanism but acting automatically to grip the cut material when said restoring mechanism moves said kerf-cutting mechanism toward initial position.
191. In a mining machine, the combination with a supporting frame, of a loop chain core-cutter having an unobstructed core opening therethrough and mounted on said 20 frame for swinging feeding movement on a substantially horizontal axis, means for driving said core-cutter, mechanism for feeding said core-cutter while being driven, means for actuating said core-cutter in reverse direction, and a device movable with said core-cutter freely under the core produced by the latter but engaging the cut material when said core-cutter is moved in the reverse direction.
192. In a mining machine, the combination with a supporting frame, of an axle mounted thereon for movement relatively thereto on a horizontal axis, a loop chain core-cutter having an unobstructed core 30 opening therethrough and comprising a U-shaped frame mounted on said axle, means for adjustably securing the legs of said U-shaped frame to end portions of said axle to enable the radial length of the loop chain 35 core-cutter to be varied, and means for operating said loop chain core-cutter including the movement of said axle on such horizontal axis to effect feeding movement of the core-cutter.
193. In a mining machine, the combination with a supporting frame, of a loop chain core-cutter having an unobstructed opening therethrough, means for mounting said loop chain core-cutter on said supporting frame 40 for feeding movement on a horizontal transverse axis, means for operating said loop chain core-cutter to cut a kerf in the general direction of the floor of the mine to form an undercut and a pair of side kerfs 45 and a back communicating kerf to form a depending pillar of material in an upright mine wall, conveyer mechanism the front of which is arranged to enter said undercut, and means for moving the front portion 50 of the conveyer mechanism upwardly.
194. In a mining machine, the combination with a supporting frame, of a loop chain core-cutter having an unobstructed core opening therethrough and pivoted to 55 said supporting frame to swing about an axis transverse to the vertical and horizontal axes of the machine, and means for operating said loop chain core-cutter including feeding movement thereof to cut forwardly and upwardly to produce a depending pillar 70 of material in an upright mine wall.
195. A mining machine comprising a supporting frame, a loop chain core-cutter having an unobstructed core opening therethrough and comprising a chain cutter and 75 stirrup for carrying the same, a swinging support for said stirrup mounted on said supporting frame for adjustment on a horizontal axis, means for adjustably holding said swinging support on said supporting 80 frame to adjust the elevation of the horizontal swinging axis of said loop chain core-cutter, and means for operating said loop chain core-cutter including swinging feeding movement thereof on such horizontal 85 axis at its adjusted elevation.
196. In a mining machine, the combination with a supporting frame, of kerf-cutting mechanism mounted on said frame, means for operating said kerf-cutting mechanism including feeding movement thereof, means connected to said kerf-cutting mechanism and movable freely in feeding direction along the kerf produced by said kerf-cutting mechanism, and mechanism for moving said last-named means in the opposite direction to cause the same to grip the cut material and dislodge the same.
197. In a mining machine, the combination with a kerf-cutting mechanism comprising a cutter frame, of means for operating said kerf-cutting mechanism including the feed thereof, restoring mechanism connected to said cutter frame and movable therewith into the kerf produced thereby, and mechanism movable freely with said restoring mechanism in the feeding direction of said kerf-cutting mechanism but acting automatically to grip the cut material when said restoring mechanism moves said kerf-cutting mechanism toward initial position.
198. In a mining machine, the combination with a kerf-cutter, of a frame for supporting the same, means for driving said kerf-cutter, mechanism for feeding said 115 kerf-cutter while being driven, means for actuating said kerf-cutter in reverse direction, and a device movable with said kerf-cutter freely into the kerf produced by said kerf-cutter but engaging the cut material 120 when said kerf-cutter is moved in the reverse direction.
199. In a mining machine, the combination with a loop chain cutter, of a U-shaped frame for said chain cutter, an axle, a supporting frame for said axle, means for adjustably securing the legs of said U-shaped frame to end portions of said axle to enable the radial length of said loop chain cutter to be varied, means for driving said chain cutter.

- ter, and apparatus for moving said axle on said supporting frame to effect feeding movement of said U-shaped frame and the chain cutter mounted thereon.
- 5 200. In a mining machine, the combination with a supporting frame, of kerf-cutting mechanism mounted thereon in position to cut a kerf in a general horizontal direction and in an upward direction to form a 10 pair of side kerfs and a back kerf enclosing a depending pillar of material, means for operating said kerf-cutting mechanism including upward feed thereof to form such pillar, removing means arranged to enter beneath the pillar of material to receive and carry off the dislodged material, and means for breaking the depending pillar whereby the separated portion may be caught and removed by the removing means.
- 15 201. In a mining machine, the combination with a supporting frame, of kerf-cutting mechanism mounted on said supporting frame in position to cut a kerf in the general direction of the floor of a mine to form an undercut and to cut a pair of side kerfs and a back communicating kerf, means for operating said cutting mechanism to cut such floor kerf and said side and back kerfs to form a depending pillar of material in an 20 upright mine wall, conveyer mechanism whose front portion is arranged to enter the undercut, and means for moving the front portion of the conveyer mechanism upwardly.
- 25 202. A mining and loading machine comprising core-cutting mechanism, a frame for supporting said core-cutting mechanism in suspended position initially, means for operating said core-cutting mechanism to cut an upright core of material in a mine wall, and mechanism for moving back from the mine wall the section of severed material, while at the same time restoring said core-cutting mechanism to initial position and continuing 25 the transfer of such severed material toward loading position after said core-cutting mechanism has been restored to initial position.
- 30 203. In a mining machine, the combination with a supporting frame, of an axle carried thereby and journaled for rotation relatively thereto, an endless chain cutter, a cutter frame supported wholly by said axle for rotation therewith and having an unobstructed core opening therethrough, means for driving said chain cutter around said cutter frame and longitudinally along said axle, means for guiding said chain cutter to and along said axle, and means for rotating 35 said axle to effect the feed of said chain cutter.
- 35 204. In a mining machine, a U-shaped cutter frame having an unobstructed core opening therethrough, an axle on which said cutter frame is mounted, and means for ad- justably securing the arms of said U-shaped frame to said axle whereby the area included within said frame may be increased or diminished.
- 40 205. In a mining machine, a U-shaped cutter frame having an unobstructed core opening therethrough, an axle for supporting said cutter frame, clamping plates for adjustably holding said cutter frame to the ends of said axle, and means for removably 45 securing said clamping plates in position.
- 45 206. In a mining machine, a U-shaped cutter frame having an unobstructed core opening therethrough, an endless chain cutter mounted on said cutter frame, and removable clamping plates for securing the arm of said cutter frame to the ends of said axle whereby said cutter frame may be adjusted relative to said axle for tightening said cutter chain and for increasing or di- 50 minishing the area included within said cutter frame.
- 50 207. In a mining machine, the combination with a loop chain core-cutter, of a U-shaped frame having an unobstructed core opening therethrough, an axle for supporting said frame, means for guiding said cutter along a part of said axle at one side of the loop formed by said cutter, a curved guide located at one end of the axle for 55 changing the direction of movement of said cutter at one corner of the loop formed thereby, a sprocket wheel located at the end of the axle opposite said curved guide for guiding said cutter at another corner of the 60 loop formed thereby and for operating said cutter, and means carried by said axle for driving said sprocket wheel.
- 55 208. In a mining machine, the combination with loop chain core-cutting mechanism having an unobstructed core opening therethrough, of an axle for supporting said loop chain core-cutting mechanism, an adjustable pivoted bracket for supporting both 65 said axle and said core-cutting mechanism, and means for moving said bracket to adjust the elevation of said axle and the core-cutting mechanism carried thereby.
- 60 209. In a mining and loading machine, the combination with a frame, of core-cutting mechanism mounted thereon, means for operating said core-cutting mechanism including arcuate feed thereof, and an apron conveyer mounted on said frame in position for receiving the material dislodged by said 70 core-cutting mechanism and transferring such material toward loading position.
- 65 210. In a mining and loading machine, the combination with a supporting frame, of a guarded chute, core-cutting mechanism associated with the receiving end of said chute, and a flexible apron conveyer for transferring dislodged material toward loading position.
- 70 211. A mining machine comprising a sup- 75

- porting frame, loop chain core-cutting mechanism for entirely cutting out from a mine wall adjacent said frame a crescent-shaped core of material, means for operating 5 said loop chain core-cutting mechanism, a support connected to said frame for receiving all of said core directly from its cut position in the mine wall, and means for moving said support together with the core 10 thereon back from the mine wall.
212. In a mining machine, the combination with cutting mechanism, of means for actuating said cutting mechanism, mechanism for slowly feeding said cutting 15 mechanism forward during its actuation, a device for receiving the material cut from the mine wall by said cutting mechanism, and apparatus for effecting the quick return of said cutting mechanism to initial position 20 and at the same time returning said receiving device to move the material thereon back from the mine wall.
213. In a mining machine, the combination with supporting framework, of core- 25 cutting mechanism mounted thereon and having an unobstructed core opening therethrough, means mounted on said framework and movable relatively thereto under the core of cut material in position to receive 30 the severed section directly from its original position in the mine wall and carry the dislodged material thereon away from the mine wall when said receiving means is moved relatively to said framework away from the 35 mine wall, and means for operating said core-cutting mechanism including the feed thereof.
214. In a mining machine, the combination with a frame, of a chute mounted 40 thereon, means for adjusting the position of said chute adjacent the mine wall, and means for taking a long block of solid material from its position in the mine wall and delivering it intact directly therefrom 45 into said chute.
215. In a mining and loading machine, the combination with an elongated frame comprising a chute open at both ends, of a reciprocating carrier movable back and forth 50 along said chute, means mounted on the forward portion of said frame in position to dislodge material from a mine wall in advance of said frame, and means for operating said carrier from a receiving position 55 below the range of operation of said dislodging means, toward loading position to effect the transfer of the dislodged material directly from its position in the mine wall into the forward open end of said chute and 60 along the latter out of the open rear end thereof.
216. In a mining and loading machine, the combination with a frame having a longitudinal chute open at its forward end and 65 its rear end, of mechanism for dislodging material from the mine wall for movement into the forward open end of said chute, and a reciprocating device for transferring material along said chute toward loading position. 70
217. In a mining and loading machine, the combination with a frame having a chute extending longitudinally thereof, of dislodging mechanism mounted on said frame for operation in advance thereof, mechanism 75 adapted to span the space between the forward open end of said chute and the mine wall for receiving the dislodged material as it falls from the mine wall, and means for reciprocating said receiving means to carry 80 the dislodged material along said chute to the rear open end thereof and return forwardly along said chute to receiving position for another load.
218. In a mining and loading machine, the combination with a frame having a longitudinal chute open at its forward end and 85 at its rear end, of mechanism for dislodging material from a mine wall for movement into the forward open end of said chute, a reciprocating carrier movable back and forth along said chute, and means for moving said carrier into position for receiving 90 the dislodged material and for moving said carrier along said chute to transfer the dislodged material toward loading position. 95
219. In a mining and loading machine, the combination with a frame having an open-ended chute mounted thereon, of dislodging mechanism mounted on the forward 100 end of said frame in position to dislodge material in advance thereof and in alignment with said chute, a reciprocable carrier movable back and forth along said chute and beyond the forward end thereof in position 105 for receiving dislodged material, and means for moving said carrier from such receiving position along said chute toward loading position.
220. In a mining and loading machine, the combination with a frame having a chute extending longitudinally thereof, of dislodging mechanism mounted on said frame for operation in advance thereof, an elongated reciprocable carrier adapted to move 110 back and forth along said chute and extend forwardly in advance thereof, and means for moving said carrier into position for receiving material directly from said dislodging mechanism and for moving said carrier 115 rearwardly along said chute to transfer such material toward loading position. 120
221. In a mining and loading machine, the combination with a frame, comprising a chute, of core-cutting mechanism mounted 125 on the forward end of said chute in position to dislodge an upright core of material from a mine wall, and conveyor mechanism mov-

able along said chute to transfer toward loading position the dislodged material from the base of the mine wall where it falls.

222. In a mining and loading machine, the combination with a frame comprising a longitudinal chute with its forward receiving end adjacent the base of a mine wall, of core-cutting mechanism mounted on the forward end of said frame to swing on a horizontal axis in position to dislodge an upright core from a mine wall, and flexible conveyer mechanism extending along said chute toward loading position from a position for receiving the dislodged material directly from said core-cutting mechanism.

223. A mining and loading machine comprising a supporting frame, a loop chain core-cutter comprising a cutter frame having an unobstructed core-opening therethrough for guiding the chain around the core cut by said cutter, means for operating said cutter including arcuate feed thereof to cut an arcuate core, and means in position for carrying the cut core of material in an arcuate path away from the mine wall immediately after being cut by said cutter.

224. A mining and loading machine comprising a supporting frame, means mounted thereon for severing a crescent-shaped block of material in its native bed adjacent said frame, and mechanism mounted on said frame and movable relatively thereto in position for carrying the severed block bodily

away from its severed position in an arcuate path of travel immediately after being severed.

225. In a mining machine, a cutter head comprising an axle, a loop cutter carried by said axle, a support for said axle, and means for connecting said axle to said support for adjustment relative thereto to vary the effective radius of said loop cutter while the latter is supported by the floor of the mine chamber.

226. In a mining machine, the combination with a core-cutter, of means for operating said core-cutter, a conveyer in position to receive dislodged material directly from said cutter by gravity immediately after being cut, and means for operating said conveyer.

227. In a mining machine, the combination with a loop chain core-cutter, of means for operating the same including the feed thereof in an arc, and a conveyer in position to receive dislodged material from said core-cutter directly by gravity throughout the arcuate range of movement thereof.

In testimony whereof I have signed my name to this specification, in the presence of two subscribing witnesses, on this 28th day of September, A. D. 1914.

EDMUND C. MORGAN.
